UNITED STATES PATENT OFFICE.

EDWIN F. TRAPP, OF VALLEY STREAM, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 19, 1924. Serial No. 714,234.

To all whom it may concern:

Be it known that I, EDWIN F. TRAPP, a citizen of the United States of America, residing at Valley Stream, Long Island, in 5 the county of Nassau and State of New York, have invented certain new and useful Improvements in Telephone-Exchange Systems, of which the following is a full, clear, concise, and exact description.

10 This invention relates to telephone exchange systems and more particularly to a testing system for use in machine switching offices for testing selector and connector units.

15 An object of this invention is to provide an improved testing system.

Switching units of an automatically operated telephone exchange are made up of control apparatus, relays and auxiliary circuits to control their automatic progression and to further control other switching units and the lines to which connections are established. A large number of such switching units are required in a system of this 25 kind, any one of which may be arbitrarily selected when idle to complete a service connection. Thus, it is apparent that a switching unit giving inefficient service is not immediately noticed. Since the apparatus of a 30 switching unit requires adjustment within limited variations, it is important that these units be regularly tested to determine their ability to render efficient service. In order to reduce the cost of such maintenance, it 35 is desirable to use a testing system requiring a limited amount of manual operation, confining the latter for the most part of the operation of keys and the observation of lamp signals.

40 While the invention about to be disclosed may with slight variations be applied to test any type of selector and connector switches, it has been particularly arranged for testing district selector and line finder 45 circuits of the type disclosed in the application of Frank S. Irvine, Serial No. 602,948, filed Nov. 24, 1922 and in the following patents to Frank S. Irvine: 1,461,528, issued July 10, 1923; 1,505,710, issued Aug. 19, 50 1924 and 1,507,966, issued Sept. 9, 1924.

A feature of this invention resides in the use of a common testing device for particularly testing the operation of selector switches of the above mentioned type.

A further feature of this invention relates to the provision of means for operating selector switches of the above mentioned type in simulation of the manner in which such switches function under actual service conditions and for observing through the medium of supervisory apparatus the accuracy with which these switches function. 55

A further feature resides in the manner of establishing a connection between the testing device and the selector to be tested. 60

A further feature relates to a method of determining whether the line finder selector is in contact with the desired line.

A further feature may be found in the test of the message register charging circuit. 70

A further feature is the test of the coin collect and return circuit.

A further feature resides in the method of repeating any one of the three parts of 75 a routine test on the same selector any number of times.

A further feature resides in the provision of means for selecting out of all the associated selectors one particular selector for 80 test.

A further feature is an arrangement whereby when two test circuits of the type herein disclosed are employed in the same office, the one first seizing a district for test 85 may block the second until the first has caused the district to select its associated terminals.

Further features may be found in the method of determining the type of selector 90 circuit to be tested, the apparatus for advancing from one circuit to another, and the means for sending a series of impulses through the test circuit in the sender which has been associated with a district to cause 95 the district to select a set of terminals associated with the test circuit.

The apparatus to be tested consists of a line finder district circuit, shown in Figs. 3 and 4, which is associated by means of proper conductors to line finder connectors of the type shown in Fig. 10. Each twenty district and line finder circuits have associated with them a common start circuit of the type shown in Fig. 1, of a character similar to that disclosed in the above mentioned Irvine patent. A line circuit similar to the ordinary subscriber's line circuit shown in 100 105

Fig. 2 is permanently associated with the test circuit and the line finder selector is caused to select this circuit. While it will be shown that this test circuit may be used to test district selector and line finder circuits of the coin collect, flat rate or the message rate one and two party type, for the sake of simplicity of disclosure, only the two party message rate circuit has been shown. For the coin collect type district circuit reference may be had to Fig. 2 of the patent of E. H. Mills, No. 1,504,261, issued Aug. 12, 1924, and for flat rate and message register single party type reference may be had to the application of F. S. Irvine, Serial No. 602,948, also above noted.

Reference may now be had to the accompanying drawings:

Fig. 1 shows a start circuit of the type herein referred to having a regular and an emergency circuit. There is also associated with the two circuits an auxiliary test circuit for testing the line finder selector. Its function will become more apparent after the description of operation has been given.

Fig. 2 shows the relays and apparatus which are ordinarily associated with a subscriber's line.

Fig. 3 shows a panel line finder selector switch, a party selector stepping switch and the necessary control relays.

Fig. 4 shows a district panel type selector switch, its associated repeating coil, relays and sequence switches in addition to a sender selector and a representation of a sender. Since this sender circuit is not a part of the invention and since it is fully disclosed in Patent No. 1,395,977 issued November 1, 1921 to F. A. Stearn and F. J. Scudder, it has been represented here by the rectangle 430.

Figs. 5 to 13, inclusive, show the arrangement of the test circuit itself.

Fig. 5 contains a duplication of the district selector frame terminals shown on Fig. 4, the connecting conductors being left out for the sake of clearness. A second test circuit, which is similar in all respects to that shown on Figs. 5 to 13, inclusive, is represented diagrammatically by the rectangle 500 in Fig. 5. Auxiliary relays, interrupters and resistance elements together with signaling lamps are also shown.

Fig. 6 contains additional lamps, relays and conductors and also a key which, when operated, causes the test circuit to repeat a complete cycle of routine tests.

Figs. 7 and 10, when taken together, show the means for selecting the circuits for test. The system used is a pyramid system. Selector switches 700 and 1000 are the master switches. These switches have associated with their terminals, twenty group switches of the type indicated at 710 and 1020. In Fig. 7 the terminals of each group switch

are connected to a start circuit as shown in Fig. 1, conductors 717 to 721, inclusive, on Fig. 7 being connected to conductors 717 to 721, inclusive, on Fig. 2. In addition to the master and group switches, there are also line finder switches shown in Fig. 10 which are connected by means of their terminals and conductors 1049 to 1051, inclusive, through Fig. 2 to the line finder circuit of Fig. 3. While only one master, one group and two line finder selector switches have been shown, it should be understood that any number of these switches may be employed with slight modification of the drawings without departing from the spirit of the invention. The number of switches provided depends upon the number of district and line finder circuits to be tested. Each line finder switch has access to twenty line finder and district circuits, each group switch has access to twenty line finder selectors and each master switch controls twenty group switches. Therefore, when one master switch is employed, access may be had to twenty times twenty or four hundred district and line finder circuits. It is the usual custom to employ two master switches in each office so that a total of eight hundred circuits may be subject to routine test.

Fig. 8 shows the test circuit, its controlling sequence switch and associated cams, a dial and key for selecting a particular circuit to be tested, and within the dash-dot rectangle, a pulsing sequence switch is provided with two controlling relays. The cuttings of the cams of this sequence switch differ from the standard sequence switch in that they are cut in twenty positions. Besides, the cuttings of cam 854, which are written within circles, are special cuttings arranged to be closed $2\frac{1}{4}$ degrees before to $2\frac{1}{4}$ degrees after the positions indicated.

Fig. 9 shows a sequence switch known as a class sequence switch which takes settings determined by the particular type of the district circuit which is under test. A number of lamps are shown which light as a visual indication of the type of circuit under test. A key is also shown which controls the lighting of these lamps. Another key 920 is provided for making a false charge test which will be more fully explained herein-after.

Fig. 11 discloses a number of keys which are essential to the operation of the circuit, a start key 1 for controlling the start of a routine test, control advance key 2 for advancing the test circuit when it halts due to the development of trouble, and a pass busy key 4 for enabling the line finder switch to pass over the terminals of a busy line finder district circuit and proceed to test the next selector. Keys 3, 7 and 8, respectively, are used to repeat the series of tests made in the first, second and third revolutions of the test

sequence switch 800. Key 5, when operated, effects the complete restoration of the test circuit. If it is desired to make a test upon a particular circuit, key 6 is operated in conjunction with the dial and keys shown in Fig. 8. Fig. 11 also contains a busy register to record the number of times a busy terminal has been passed over, a single test register which records the number of single tests made, and a lamp signal indicating that the circuit under test is busy.

Fig. 12 contains a complete test register for indicating the number of complete tests which have been made and an arrangement of relays and lamps for indicating when more than one group selector has been stepped off normal.

In Fig. 13 is shown a class stepping switch which operates in synchronism with the line finder connector switch and by an arrangement of lamps indicates at any time the number of the district circuit under test. A group of relays is also disclosed here which are employed for controlling the setting of class sequence switch 900 of Fig. 9. Within the dot-dash rectangle is shown a time alarm circuit which is similar in all respects to that disclosed in the application of Arnold S. Bertels and Edwin F. Trapp, Serial No. 679,312 filed December 8, 1923. At the extreme right of this figure is indicated a series of lamps which light in order as an indication of the number of the line finder connector which is at each moment employed. Only two of these lamps have been shown connected, the first and the twentieth, since only the first and the twentieth line finder connectors have been disclosed on Fig. 10. But it should be understood that each of the other lamps is connected to a line finder connector.

General description.

The operation of the start key, shown in Fig. 11, at the beginning of a routine test causes the time measure switch of Fig. 13 to begin to measure time. The operation of this key also causes the master selector switch to step to its first terminal. The test circuit is then connected to the first group switch, which, in turn, is caused to step to its first terminal, in turn, causing the first line finder connector switch to rotate to its first terminal.

A condition is placed upon the first terminal of the line finder connectors in order to test the type of circuit. All of the line finder and district selector circuits associated with any one line finder connector switch are of the same type, being either one or two party message rate, coin collect or flat rate circuits. With the line finder connector switch on terminal 1 a test is made to determine which type is associated with the switch. Upon this determination

the class relays of Fig. 13 and the class sequence switch of Fig. 9 are set in the proper position to direct the test circuit in its selection of the kind of tests to be made. It should be understood that different tests are made on the different types of circuits.

Upon the completion of the class switch setting, the line finder connector steps to its next terminal, thus connecting the test circuit to the first line finder and district circuit to be tested. Since it is possible that this circuit may not be in condition for test, certain preliminary tests must be made.

These consist of a test for a spare terminal and for a busy or idle circuit. If the terminal upon which the line finder connector is standing is spare, that is, it is not connected to any circuit the connector is caused automatically to pass over this terminal to the next terminal. If the circuit is

found to be busy either in regular traffic or because it has been artificially made busy, the connector switch will remain upon the terminal and wait for it to become idle. A lamp signal is lighted as an indication that the terminal is busy and, if it is so desired, the operator may cause this terminal to be passed over. If the circuit to be tested is found in an idle condition the line finder is

caused to perform the same functions necessary for the completion of an ordinary call. The test line is hunted for and tests are made to determine whether or not the line finder elevator moves upwardly and also whether or not it comes to rest on the proper line.

The district circuit is then caused to advance to its second position to select an idle sender. Upon the selection of the sender a dialing path is completed through the district to the test circuit. The pulsing sequence switch of Fig. 8 then proceeds to transmit a series of impulses in simulation of the code transmitted by the calling dial.

This code is registered on the registers of the sender and the district is advanced, making brush and group selections and hunting for the trunk leading to the test circuit. The code transmitted to the sender is such that it would cause the district circuit to rest in a position in which its repeating coil is shunted out of the talking circuit.

Various special operate, non-operate and release conditions are placed in the circuit of both of the district supervisory relays and the behavior under these conditions is reported in the test circuit. Upon completion of the relay tests, the district is released, permitting its return to normal. The test circuit sequence switch is then caused to make a second revolution. Another code is

transmitted, this second being such that the district selector is caused to stop in a position in which the repeating coil is included in the talking circuit. Tests similar to those made during the first revolution of the test

sequence switch are again made on the district supervisory relays and the district circuit is advanced into its message register charging position where it is tested for the registration of a call made by the first party of a two-party line. The registration of a call made by the second party of the two-party line is tested on the third revolution of the test circuit sequence switch. During this revolution the same code is transmitted as was transmitted during the second revolution, the district circuit assuming the same position.

Upon the completion of these tests the line finder connector is stepped to its next terminal and the next line finder and district selector is tested in the same manner as the first. When all of the line finder and district circuits associated with the line finder connector are tested, the group switch is advanced to its next terminal and the test is conducted on the circuits associated with the next line finder connector. When the group switch has made a complete revolution the master switch advances to its next terminal, permitting the circuits associated with the next group switch to be tested. If a second master switch is provided, the circuits associated therewith are tested upon the completion of the tests of those connected to the first master switch.

Initiation of test.

It is thought that the invention will be more apparent from a detailed description of the operation of a routine test. An operator desiring to make a complete test upon all the district selector circuits and line finder circuits to which this test circuit has access, depresses a start key 1. Upon the operation of this key, a circuit is closed from grounded battery, winding of the power magnet of sequence switch 800, lower right contact of cam 801, conductor 802, left back contact of relay 1201, outermost right back contact of relay 1202, conductor 1203, operated contact of key 1 to ground at the normal contact of key 2. The power magnet of sequence switch 800 is energized in this circuit, moving this sequence switch from position 1 to position 2. A circuit is also completed from grounded battery, winding of start relay 1204, conductor 1205 to ground at the operated contact of key 1. Relay 1204 energizes in this circuit. The operation of the start key 1 also causes the time alarm circuit shown in Fig. 13 to function by completing a circuit for the energization of relay 1301. This circuit may be traced from grounded battery, winding of relay 1301, brush arm 1302 and its associated normal contact, conductor 1303 to ground at the operated contact of start key 1. The functioning of this time alarm circuit will be more fully explained hereinafter.

With sequence switch 800 in position 2, a circuit may be traced from ground, right back contact of relay 803, conductor 804, left normal contact of relay 601, outer left normal contact of relay 602, left normal contact of relay 603, conductor 604, lower right contact of cam 805, upper left contact of cam 806, conductor 807, left winding of relay 605, conductor 606, brush arm 701 of the first master selector switch 700 and its associated normal terminal, conductor 707, right back contact of relay 607, conductor 608, brush arm 1001 of the second master selector switch 1000 and its associated normal terminal through the winding of relay 1007 to grounded battery. Relays 605 and 1007 are energized in this circuit. The energization of relay 1007 provides operating paths for the stepping magnets of master switches 700 and 1000. The circuit for master switch 700 may be traced from grounded battery, winding of magnet 700, armature and back contact of the magnet, right operated contact of relay 1007, conductor 1008, right contacts of cam 808, conductor 809, armature and back contact of relay 609, inner right armature and back contact of relay 610, conductor 611, normal contacts of keys 6, 3, 7, 8 and 2, conductor 12, back contact of relay 1201, conductor 1206, intermediate back contacts of relays 1304 and 1305, next to the inner back contacts of relays 1306 and 1307, conductor 1308, upper left and lower right contacts of cam 810 to ground. The energization of relay 605 completes a short circuit around the winding of relay 612. This short circuit may be traced from one side of the winding of relay 612, front contact of relay 605, conductor 613, lower right contact of cam 808, conductor 1008, right front contact of relay 1007, armature and back contact of stepping magnets 700 and 1000 in parallel, inner left front contact of relay 1007, conductor 1009, lower right and upper left contacts of cam 811, conductor 812 back to the other side of the winding of relay 612.

Advance of master selector.

This short circuit is broken upon the operation of the master stepping magnets 700 and 1000 and relay 612 then becomes energized. A circuit may then be traced from grounded battery, winding of the power magnet of sequence switch 800, lower left contact of cam 801, conductor 813, outer right back contact of relay 1207, conductor 1208, front contact of relay 612, back contact of relay 614, conductor 615, normal contacts of key 6, conductor 13, right back contact of relay 1209, conductor 1210 to ground at the upper left contact of cam 901. Sequence switch 800 is then advanced out of position 2 into position 3. As this sequence switch leaves position 2, relays 605, 120

612 and 1007 and magnets 700 and 1000 de-energize. The release of the two latter magnets causes the brush assemblies of their associated switches to step to their 5 first normal terminals. It will be noted that the energization of relay 1007 completed an obvious circuit for relay 1010. Relay 1010 closes a circuit from grounded battery through its left armature and front contact, lamp 1011, conductor 1012 to ground at the operated contact of key 902. (This key may be operated at the beginning of a test when lamp signals are desired). Lamp 1011 lights as an indication that the master 10 switch has been stepped off normal.

Advance of group selector.

As soon as the master switch reaches its first terminal, a holding circuit is completed 20 for relay 1010 from grounded battery, winding of relay 1010, brush arm 1006 and its associated first off normal terminal, left winding of relay 1013 to ground. The completion of this circuit causes the energization 25 of relay 1013, which in turn completes a circuit from grounded battery, resistance 1015, inner left front contact of relay 1013, conductor 1014, intermediate right back contact of relay 1202, winding of relay 1211, conductor 1212 to ground at the normal contact of key 5. Relay 1211 does not receive sufficient current to operate at this time. The energization of relay 1013 also completes 30 a circuit from grounded battery, right front contact of relay 1013 through lamp 1016, conductors 1017 and 1012 to ground at the contact of key 902. With sequence switch 800 in position 3 and the master switches on terminal 1, a circuit may be traced from 35 grounded battery, winding of relay 1018, brush arms 1021 and 711 and their associated normal terminals, brush arm 1002 and its associated first terminal, conductor 708, right winding of relay 605, conductor 616, upper right contacts of cams 806 and 805, conductor 814, inner left back contact of relay 602, left back contact of relay 601, conductor 804 to ground at the right back contact of relay 803. Relays 1018 and 605 are 40 energized in this circuit. Relay 1018, upon operating, completes a circuit from grounded battery, through the windings, armatures and back contacts of stepping magnets 1020 and 710 in parallel, outer front contact of relay 1018, conductor 1008, right contacts of cam 808, conductor 809, normal contacts of relay 609, inner right back contact of relay 610, conductor 611, normal contacts of keys 6, 3, 7, 8 and 2 in series, conductor 12, outer right back contact of relay 1201, conductor 1206, intermediate back contacts of relays 1304 and 1305, next to the inner back contacts of relays 1306 and 1307, conductor 1308 to ground at the upper left and lower right 45 contacts of cam 810. Magnets 710 and 1020

are energized in this circuit. The energization of relay 1018 closes a short circuiting path around the winding of relay 612. This circuit may be traced from one side of the winding of relay 612, conductor 812, upper 50 left and lower right contacts of cam 811, conductor 1009, front contact of relay 1018, back contact of stepping magnet 1020, outer front contact of relay 1018, conductor 1008, lower right contact of cam 808, conductor 75 813, front contact of relay 605 to the other side of the winding of relay 612. When magnets 710 and 1020 attract their armatures this short circuit is opened and relay 612 is energized, completing a circuit from 80 grounded battery, winding of the power magnet of sequence switch 800, lower left contact of cam 801, conductor 813, outer right back contact of relay 1207, conductor 1208, front contact of relay 612, back contact of 85 relay 614, conductor 615, normal contacts of key 6, conductor 13, right back contact of relay 1209, conductor 1210 to ground at the upper contact of cam 901. Sequence switch 800 is advanced from position 3 into position 90 4 over this circuit.

Selection of line finder.

As sequence switch 800 leaves position 3, 95 relays 612, 605 and 1018 and stepping magnets 710 and 1020 deenergize. The deenergization of the stepping magnets causes the brush assemblies of the associated selector switches to step to the first terminal. A circuit may now be traced from grounded battery, winding of relay 1027, brush arm 1026 and its associated first terminal, winding of relay 1019, right winding of relay 1013 to ground. Relays 1027, 1019 and 1013 energize in this circuit. When relay 1019 at 100 attracts its armatures, a circuit is closed from ground through the inner front contact of relay 1019, conductor 1037 through the winding of relay 603 to grounded battery, energizing this relay. A circuit may also be 105 traced from grounded battery through the winding of relay 1029, brush arm 1022 and its associated first terminal, conductor 1038, right winding of relay 501, lower right contact of cam 806, conductor 814, inner left 110 back contact of relay 602, left back contact of relay 601, conductor 804 to ground at the right back contact of relay 803. Relays 1029 and 501 energize in this circuit. The energization of relay 1029 completes a circuit 115 from grounded battery, winding of stepping magnet 1030, armature and back contact of the magnet, outer front contact of relay 1029, conductor 1008, right contacts of cam 808, conductor 809, back contact of relay 120 125 609, inner right back contact of relay 610, conductor 611 through the normal contacts of keys 6, 3, 7, 8 and 2 in series, conductor 12, outer right back contact of relay 1201, conductor 1206, intermediate armatures and 130

back contacts of relays 1304 and 1305, next to the inner back contacts of relays 1306 and 1307, conductor 1308, upper left and lower right contacts of cam 810 to ground. The line finder selector magnet 1030 becomes energized and the short-circuiting path for relay 612, which, as can obviously be seen, was transferred through the back contact of stepping magnet 1030, is now broken and this relay operates. Sequence switch 800 is now advanced from position 4 into position 5 over a circuit which may be traced from grounded battery through the winding of the power magnet of this sequence switch, lower left contact of cam 801, conductor 813, outer right back contact of relay 1207, conductor 1208, front contact of relay 612, back contact of relay 614, conductor 615, normal contact of key 6, conductor 13, right back contact of relay 1209, conductor 1210 to ground at the upper contact of cam 901. The energization of relay 1027 completes a circuit from grounded battery through its right front contact through lamp 1326 over conductor 1012 to ground at the contact of lamp key 902. Lamp 1326 is lighted as an indication that the first line finder connector has been associated with the group switch and is now off normal. As sequence switch 800 leaves position 4, relays 612, 501 and 1029 and stepping magnet 1030 deenergize, the release of the latter magnet causing its brush assembly to step to its first terminal.

Positioning of class circuit.

In position 5 of sequence switch 800 a circuit is in existence from grounded battery, through the winding of relay 1315, conductor 1327, upper contacts of cam 815, conductor 816, brush arm 1313 and its normal terminal, conductor 1328, outermost right back contact of relay 1213, conductor 1214 to ground through the lower contact of cam 903. Relay 1315 operates in preparation for setting the proper class relays. These relays, designated 1304, 1305, 1306, 1307 and 1316, are operated either singly or in groups in series with relay 1317 as determined by the particular class of district circuit to which the connector switch associated with magnets 1030 and 1040 (and other magnets not shown) are connected. The various types of district selector and line finder circuits to which this test circuit has access, are message register, one and two party, coin-collect and flat rate, but for simplicity of disclosure only the message-rate, two party district selector and line finder circuit have been shown. The application of this test circuit to the other types of district selector and line finder circuits will become obvious after the following description has been made.

Assuming, then, that two party district

selector and line finder circuits are connected to the terminals of the connector bank controlled by magnet 1030, it will be seen that the energization of class relay 1315 will complete a circuit for energizing relays 1307 and 1317. This circuit may be traced from grounded battery, brush arm 1311 and its associated normal terminal, windings of relays 1317 and 1307 in series, innermost front contact of relay 1315, conductor 1331, brush arms 1034, 1024 and 1004 and their associated first terminals, conductor 1047, upper right contact of cam 815 to ground over the circuit previously described for the operation of relay 1315. Relays 1307 and 1317 are energized. Relay 1317, by opening its back contact, prevents the premature return to normal of the class selector switch controlled by magnet 1310. Relay 1307, upon energizing, completes a locking circuit for itself through its innermost front contact, conductors 1329 and 1215 to ground at the normal contact of key 5. Upon the energization of relay 1307, sequence switch 900 is advanced into position 2, which is the first position assumed by the sequence switch in preparation for testing two party, message-rate district and line finder circuits. The circuit for advancing this sequence switch may be traced from grounded battery, winding of the power magnet of sequence switch 900, lower left contact of cam 904, conductor 905, outermost front contact of relay 1307, outermost back contact of relays 1306, 1305 and 1304, conductors 1330 and 557, upper left contacts of cam 817, conductor 818, to ground at the outer right back contact of relay 1216. As soon as the circuit for sequence switch 900 is completed, a parallel circuit is also completed for relay 1207 over conductor 1217. This relay remains operated during the advance of sequence switch 900 to prevent the premature advance of sequence switch 800 out of position 5 by opening the advance circuit for the sequence switch at its outer left armature and back contact.

If districts of the coin collect type are connected to the line finder connector, then conductor 1335 instead of 1331 is connected to the first terminals of the arcs served by brush arms 1034 and 1044 and relays 1306 and 1317 are energized in a circuit which may be traced from grounded battery, brush arm 1311 and its associated normal terminal, windings of relays 1317 and 1306 in series, next to the inner front contact of relay 1315, conductor 1335, to ground as previously described on brush arm 1034. Relay 1317, upon operating, performs the same function as above described. Relay 1306 locks through its innermost front contact to ground on conductor 1329. Sequence switch 900 is then advanced to position 5 which is the first position for testing districts of the coin collect

type. The circuit for advancing sequence switch 900 extends from battery through the winding of sequence switch power magnet 900, upper left contact of cam 904, conductor 955, outermost front contact of relay 1306, outermost back contacts of relays 1305 and 1304, conductors 1330 and 557 upper left contact of cam 817, conductors 818 and 30 to ground at the outer left back contact of relay 14.

For districts of the flat rate type conductor 1336 is connected to brush arms 1034 and 1044 and relays 1305 and 1317 are operated, the circuit for these relays extending through their windings in series, next to the outermost front contact of relay 1315, conductor 1336, to ground as previously described on brush arm 1034. Sequence switch 900 is then advanced to position 8 in a circuit which may be traced from battery through the winding of magnet 900, upper right contact of cam 904, conductor 944, outermost front contact of relay 1305, outermost back contact of relay 1304 to ground as traced on conductor 1330. Conductor 1337 is connected to brush arm 1034 as an indication that message rate single-party circuits are associated with the connector and relays 1304 and 1317 are energized in a circuit extending through the outermost front contact of relay 1315. Sequence switch 900 advances to position 2 over conductor 905 as described for districts of the message rate two-party type. When sequence switch 900 comes to rest in position 2, relay 1207 deenergizes. It should be noted that as sequence 800 entered position 5, relays 1029 and 501 were energized in a circuit which may be traced from grounded battery, winding of relay 1029, brush arm 1022 and its associated first terminal, conductor 1038, right winding of relay 501, lower right contact of cam 806, upper right contact of cam 805, conductor 814, inner left back contact of relay 602, left back contact of relay 601, conductor 804 to ground at the right back contact of relay 803. With relay 1029 energized and relay 1027 normal, a circuit for operating stepping magnet 1030 may be traced from grounded battery, winding, armature and back contact of the stepping magnet, outer front contact of relay 1029, conductor 1008, right contacts of cam 808, conductor 809, back contact of relay 609, inner right back contact of relay 610, conductor 611, normal contacts of keys 6, 3, 7, 8 and 2 in series, conductor 12, outer right back contact of relay 1201, conductor 1206, intermediate back contacts of relays 1304 and 1305, next to the inner back contact of relay 1306, next to the inner front contact of relay 1307, conductor 1332, upper left contact of cam 906, conductor 907, inner right back contact of relay 1207, conductor 1218, upper contact of cam 819, conductor 818 to ground at the

outer right back contact of relay 1216. When magnet 1030 opens its back contact, the short circuit around the winding of relay 612 is again opened and this relay energizes, preparing a circuit through its front contact for the advance of sequence switch 800 out of position 5 into position 6. This path is the same as that previously described for advancing this sequence switch from position 4 into position 5.

With sequence switch 900 in position 2, lamp 908 is lighted as an indication that the first test is in progress. A circuit for this lamp may be traced from grounded battery, upper right contact of cam 914, lamp 908 to ground at the contact of key 902. In addition a circuit may also be traced from grounded battery, upper left contact of cam 942, lamp 909 to ground at the contact of key 902. Lamp 909 is lighted as an indication that message rate type district circuits are being tested. It can obviously be seen that lamp 910 indicates that flat rate type districts are being tested and lamp 911 for coin-collect type districts. As sequence switch 800 advances out of position 5, magnet 1030 releases and its associated brush assembly is stepped to its second terminal. In position 6 of the sequence switch relays 1029, 501, 612 and 1315 release. With the brush assembly of the connector switch associated with magnet 1030 on terminal 2, a circuit may be traced from grounded battery, winding of relay 602, conductor 617, brush on 1031 and its associated second terminal to ground. Relay 602 is energized in this circuit and remains energized while the brush assembly remains upon its terminals 2 to 21 inclusive.

Special tests of line finder.

105

Spare line finder.—In position 6 of sequence switch 800, the line finder selector is tested to determine whether it is in a busy or an idle condition. The terminals of the line finder connector may be open, connected to a busy line finder or connected to an idle line finder. If there are any spare terminals on the line finder arc served by brush 1032, these terminals will be connected to conductor 1048. When there is a spare terminal on this arc, relay 1290 will be operated in a circuit extending from grounded battery through the lower contact of cam 820, conductor 821, right back contact of relay 601, conductor 618, winding of relay 1209, conductors 1219 and 1048, spare terminal of the arc served by brush arm 1032, brush arms 712 and 702 and their associated first terminals, conductor 709, lower right contact of cam 822, conductor 818, to ground at the outer right back contact of relay 1216. The energization of relay 1209 completes a circuit from grounded battery, lower left contact of cam 820, conductor 821, left wind-

130

ing of relay 14, conductor 15 to ground at the outer left front contact of relay 1209. Relay 14 will be energized in this circuit. Relay 1209 also causes the advance of sequence switch 800 out of position 6 and into 18 over a circuit which may be traced from grounded battery, winding of the power magnet of sequence switch 800, lower right contact of cam 823, conductor 824, right 10 front contact of relay 1209, conductor 1210 to ground at the upper contact of cam 901. The energization of relay 14 completes an obvious circuit for lighting lamp 16 at its outer left front contact and causes the 15 energization of relay 1216 in a circuit which may be traced from grounded battery, winding of relay 1216, conductor 1220 to ground at the right front contact of relay 14. Relay 1216 is also energized in a circuit from 20 grounded battery through its winding, conductor 620 and 1220 to ground at the right front contact of relay 14. Relays 1216 and 619 upon operating perform no useful function at this time. In position 18 of sequence 25 switch 800, relays 510 and 1029 are energized in a series circuit which may be traced from grounded battery, winding of relay 1029, brush arm 1022 and its associated first terminal, conductor 1038, right winding of relay 501 to ground at the lower contacts 30 of cam 806.

When sequence switch 800 leaves position 35 17, relays 1209 and 14 deenergize. Upon the deenergization of relay 14, lamp 16 is extinguished and relays 1216 and 619 deenergize. With relays 1214 and 1216 in their normal condition, a circuit may be traced from grounded battery through the winding, armature and back contact of magnet 1030, outer front contact of relay 1029, conductor 40 1008, right contacts of cam 808, conductor 809, normal contact of relay 609, inner right normal contacts of relay 610, conductor 611, normal contacts of keys 6, 3, 7, 8, and 2 in series, conductor 12, outer right normal contact of relay 1201, conductor 1206, intermediate normal contacts of relays 1304 and 1305, next to the inner normal contact of relay 1306, next to the inner operated contacts of relay 1307, conductor 1332, upper left contact of cam 906, conductor 907, inner right normal contacts of relay 1207, conductor 1218, upper contact of cam 819, conductor 818, to ground at the normal back contacts of relays 14 and 1216. The energization of magnet 1230 causes the brush assembly of the switch associated therewith to step to the next terminal. Relay 612 energizes when magnet 1030 opens its back contact as heretofore described. The energization of relay 612 completes a circuit from grounded battery, winding of the power magnet of sequence switch 800, normal left contact of cam 801, conductor 813, outer right normal contact of relay 1207,

conductor 1208, operated contacts of relay 612, normal contacts of relay 614, conductor 615, normal contacts of keys 6, conductor 13, right normal contact of relay 1209, conductor 1210 to ground at the upper contact of cam 901. Sequence switch 800 is advanced in this circuit from position 18 to normal position 1. As the switch leaves position 18, relays 1029, 612 and 501 deenergize. Since key 1 is still in its operated position, sequence switch 800 advances over the circuit previously described into position 2 and is immediately advanced into position 6 due to the fact that relay 602 is operated. The circuit for advancing this switch into position 6 may be traced from grounded battery winding of the power magnet of sequence switch 800, upper right contact of cam 801, conductor 825, outer left back contact of relay 1207, conductor 1221, inner left front contact of relay 602, left back contact of relay 601, conductor 804 to ground at the right back contact of relay 803. The next terminal may then be tested for busy or idle conditions. If this terminal is also spare the same process is repeated and the next terminal is tested and so on.

Busy line finder.—If the line finder connected to the terminals of the line finder selector controlled by magnet 1030 is in a busy condition, relay 17 will be energized in a circuit extending from ground brush 381 (Fig. 3), commutator segment 384, right front contact of relay 399, conductor 1050, brush arm 1034 and its associated second terminal, (Fig. 10) brush arms 1024 and 1004 and their associated first terminals, conductor 1047, lower contact of cam 815, winding of relay 17, right back contact of relay 18, conductor 19, upper contact of cam 826, conductor 827, brush arms 1005 and 1025 and their associated first terminals, brush arm 1035 and its associated second terminal, to battery on conductor 1051, through the right winding of relay 398 (Fig. 3). The energization of relay 17 in this circuit is an indication that the line finder is busy hunting for a line. If, however, a line finder under test has been made busy by the insertion of a plug 365 in a make-busy jack 366, ground will be connected to conductor 1051 and relay 14 will operate in a circuit which may be traced from ground through the sleeve and ring contacts of jack 366 and plug 365, conductor 1051, brush arm 1035 and its associated second terminal, brush arms 1025 and 1005 and their associated first terminals, conductor 827, upper contact of cam 826, conductor 19, outermost left back contact of relay 18, right winding of relay 14, conductor 821, lower contact of cam 820 to grounded battery. In either case, that is, with either relay 14 or 17 energized, the circuit through relay 18 is opened, preventing the operation of this relay and the ad-

vancement of sequence switch 800 out of position 6 in which it has come to rest. The energization of relay 14 also completes a circuit from grounded battery through the winding of relay 1216, conductor 1220, right front contact of relay 14 to ground. Another circuit may be traced from grounded battery through the winding of relay 619, conductors 620 and 1220 to the same ground 5 at the contact of relay 14. Relay 14 completes at its outer left front contact an obvious circuit for lighting lamp 16 as an indication that a busy circuit has been encountered. The energization of relay 619 10 opens the conductors 717, 718 and 719 leading to the line finder circuit, thus preventing objectionable clicks in the subscriber's receiver. The energization of relay 1216, however, performs no useful function at this 15 time. Sequence switch 800 will remain in position 6 until the busy condition is removed from the line finder or until the time alarm circuit operates.

25 *Idle line finder.*

If, however, the line finder circuit encountered by the selector switch is in an idle condition, ground is not connected to either conductors 1050 or 1051 and relays 14 30 and 17 remain in their normal condition. A circuit for relay 18 may then be traced from ground through the winding of this relay, inner left back contact of relay 14, back contact of relay 17, upper right 35 contact of cam 820 to grounded battery. The energization of relay 18 completes a circuit from ground through its innermost left front contact, conductor 20, lower left contact of cam 828, winding of 40 the power magnet of sequence switch 800 to grounded battery, advancing this sequence switch out of position 6 into position 7. It also renders the district selector circuit 45 busy by connecting ground from the left back contact of relay 621, conductor 622, outermost left front contacts of relay 18, conductor 19, upper contact of cam 826, conductor 827, brush arms 1005 and 1025 and their associated first terminals, brush 50 arm 1035 and its associated second terminal, conductor 1051, right winding of relay 398 to grounded battery, operating the latter relay. Relay 18 also completes an obvious circuit at its intermediate left front contact 55 for single test register 21. In addition, relay 1222 is energized in a circuit from grounded battery through the intermediate left front contacts of relay 18, normal contacts of key 3, conductor 22, winding of relay 1222, conductor 1223 to ground at the lower left contact of cam 901. Relay 1222 60 energizes and completes an obvious circuit for completed test register 1224.

65 The function of the start circuit of Fig. 1 will be described. A circuit may now be

traced from ground at the outer left back contact of relay 14, conductors 30 and 818, upper right contact of cam 817, conductor 829, left normal contacts of relay 619, brush arms 704 and 714 and their associated first 70 terminals, conductor 719 through the winding of relay 136 to grounded battery. Relay 136 is energized in this circuit and completes a circuit from ground at its inner right front contact winding of relay 132, inner right normal contacts of relay 132, outer left back contact of relay 102, outer left back contact of relay 152 to battery at the back contact of magnet 158. Relay 132 energizes in this 75 circuit and locks to battery at its inner right front contact.

Relay 132 upon energizing causes the energization of relays 134 and 135 in a circuit traced from grounded battery through their windings in parallel inner left back contact of relay 131 to ground 80 at the inner left front contact of relay 132. Relay 202 is also energized from grounded battery through its winding, outer left back contact of relay 203, conductor 111, outer right front contact of relay 132, conductor 90 85 90 95 95 100 105 110 115 120 125 130 130

718, brush arms 715 and 705 and their associated first terminals, conductor 722, outer right back contact of relay 619, conductor 623, upper contact of cam 830, conductor 831, winding of relay 621, conductor 625, lower left contact of cam 832, conductor 833, inner right back contact of relay 619, conductor 658, brush arm 706 and 716 and their associated first terminals, conductor 717, inner left back contact of relay 203 to ground. Relay 621 also energizes in this circuit and disconnects ground at its left back contact from conductor 622. The energization of relay 202 completes an obvious circuit for relay 204, and also connects battery through the left winding of relay 205, outer front contact of relay 202, conductor 332 to terminal 303 as a hunting condition. The energization of relay 204 completes a circuit from ground through the front contact of this relay, back contact of relay 205, left back contact of relay 206, left winding of relay 207, conductor 208, inner left front contact of relay 135, outer left back contact of relay 102, outer left back contact of relay 152 to battery at the back contact of magnet 158. Relay 207 is energized in this circuit and completes a locking circuit for itself from ground through its right winding and right front contact, conductor 209, left front contact of relay 134, left back contact of relay 100, right back contact of relay 151 through the winding of relay 102 to battery. Relay 102 is energized in this locking circuit. The energization of relay 207 completes an obvious circuit through the winding of tripping magnet 313 to ground at the outer left front contact of relay 207. Magnet 313 rotates its tripping spindle 312 in preparation for the tripping of the set of 130

brushes on the particular finder switch that is started in operation to find the calling line. The operation of relay 102 completes a circuit from grounded battery through the winding of stepping magnet 158 to ground at the inner right front contact of relay 102. This stepping magnet is energized preparatory to moving brushes 104 and 154 to their next terminals. A circuit may also be traced from battery at the outer right front contact of relay 132, winding of relay 133 right normal contacts of relay 133 to ground at the outer right operated contacts of relay 102. Relay 133 is energized in this circuit and locks through its right front contact to ground at the inner right front contact of relay 136. Relay 102, on operating, short circuits the left winding of relay 100 through its left front contact, preventing the operation of this relay and the subsequent functioning of the second group. This operation is fully explained in the above mentioned Irvine Patent No. 1,461,528. At its outer right operated contacts, relay 102 connects ground to the left normal contact of relay 103, inner right front contact of relay 134, conductor 1052, brush arm 1032 and its associated terminal, brush arms 712 and 702 and their associated terminals, conductor 709, lower left and upper right contacts of cam 811, conductor 631, inner right front contact of relay 621, conductor 723, brush arms 1003, 1023 and 1033 and their associated terminals, conductor 1049, right winding of relay 399 to grounded battery. Relay 399 operates in this circuit and locks through its inner left front contact and left winding to ground at the back contact of relay 314. A circuit is now completed from grounded battery winding of the up drive magnet 316, outer left front contact of relay 399, commutator segment 395 to ground on brush 382. Magnet 316 causes the upward movement of the brush shaft (not shown) whereby the desired brush set including brushes 304 to 307 inclusive are tripped into operative engagement with the terminals of the bank. As brush 386 progresses upwardly in response to the action of magnet 316, it makes contact with commutator segment 393 and a circuit may then be traced from ground on brush 386, commutator segment 393, inner right back contact of relay 370, conductor 210, inner left back contact of relay 101, conductor 108, inner left front contact of relay 207, through the winding of relay 206 to grounded battery. Relay 206 energizes in this circuit, opening at its left back contact the energizing circuit of relay 207, causing this relay to release. Relay 206 completes a locking circuit for itself through its left front contact, back contact of relay 205 to ground at the front contact of relay 204. Relay 206 also completes an obvious circuit through the right winding of relay 205, but

this relay does not receive sufficient flux to operate. This winding is utilized, however, to maintain the armature of relay 205 operated when it has been energized by its left hand winding. The deenergization of relay 207 opens the energizing circuit of relay 102 and this relay releases. Upon the release of relay 102, relay 131 is energized in a circuit which may be traced from grounded battery through the winding of this relay, right normal contacts of relay 131, left front contact of relay 133 to ground at the inner right back contact of relay 102. Relay 131 upon operating locks through its right front contact to ground at the outer right front contact of relay 136. The energization of relay 131 opens the energizing circuit for relays 134 and 135 causing these relays to release, restoring the start circuit to normal.

It will be remembered that when relay 102 is energized it completed a circuit for relay 399. Relay 399 in attracting its outer left armature completes a circuit for relay 425. This circuit may be traced from grounded battery through the left winding of relay 425, innermost right back contact of relay 396, outer left front contact of relay 399, commutator segment 395 to ground on brush 382. Relay 425, upon energizing, locks from battery through its right winding, lower left contact of cam 408, outer right front contact of relay 425 to ground on brush arm 491 of the sender finder switch, provided the sender finder switch is standing upon the terminals of a busy sender. The operation of this sender finder switch will be described hereinafter. The operation of relay 425 completes through its inner left front contact an obvious operating circuit for relay 494.

As the brushes 304 to 307 inclusive of the line finder selector are moved upwardly, brush 381 comes into engagement with commutator segment 384 and a circuit is completed from ground on brush 381, commutator segment 384 and thence in parallel, one path extending through the right front contact of relay 399, inner right back contact of relay 398, conductor 113, right normal contact and winding of relay 103 to grounded battery and the other path extending through the winding of relay 396 to grounded battery. Relay 103, upon energizing, opens at its left normal contact, the original energizing circuit for relay 399 but this relay remains energized through its locking circuit. Relay 396, on operating, completes a circuit for the energization of relay 398. This circuit may be traced from grounded battery through the right winding of relay 398, normal contacts of jack 366 to ground at the inner left front contact of relay 396. Relay 396 also completes a circuit for the energization of relay 392 and the

stepping magnet 403 of the sender finder switch. This circuit extends from grounded battery through the right winding of relay 392 and the winding and back contact of 5 magnet 403 in parallel, inner right front contact of relay 425, outermost right front contact of relay 396, to ground at the lower left contact of cam 489. A circuit may also be traced from grounded battery through 10 the right winding of relay 490, intermediate right front contact of relay 396, conductor 351, left contacts of cam 414, conductor 431 to ground at the inner left front contact of relay 396. Relay 490 is energized in this 15 circuit.

When the brush shaft of the line finder arrives at the terminal of the test line, relay 314 is energized over a path extending from ground through the outermost right 20 back contact of relay 370, winding of relay 314, conductor 308, upper left and lower right contacts of cam 480, brush 307, terminal 303, conductor 332, outer right front contact of relay 202, left winding of relay 25 205 to battery. Immediately thereafter or when the brush 380 centers upon the contact of the segment 383 corresponding to the test line, the locking circuit for relay 399 is opened whereupon said relay releases 30 and opens at its outer left contacts the circuit for up drive magnet 316. The release of this magnet stops the upward movement of the brushes. A circuit may now be traced 35 from grounded battery, left normal contact of relay 370, conductor 309, left front contact of relay 490, upper right contact of cam 481, winding of relay 498, outer left front contact of relay 396, right back contact of relay 399, commutator segment 384 to 40 ground on brush 381. Relay 498 energizes in this circuit and completes a circuit for the energization of relay 203. This circuit may be traced from ground through the winding of relay 203, terminal 302, brush 306, conductor 310, resistance 432, left front contact of relay 498 to battery. The energization of 45 relay 203 opens the energizing circuit of relay 202 causing this relay to deenergize.

With sequence switch 400 in position 1, 50 stepping magnet 403 associated with the sender finder switch is energized as previously described and relay 425 is locked to ground on brush 491 provided the sender finder switch is resting on the terminals of 55 a busy sender. So long, however, as brush 491 encounters terminals which are grounded, stepping magnet 403 will advance the brushes of the switch until an idle sender is found. An idle sender is characterized 60 by the absence of ground on the terminal of the arc served by brush 491. Relay 425, which is held energized to ground on brush 491, releases, opening at its inner right front contact the circuit previously traced for relay 392 and stepping magnet 403 also opens

at its inner left front contact the energizing circuit of relay 494. Relays 392 and 494 and stepping magnet 403 thereupon release. As soon as relay 392 deenergizes a circuit is completed from grounded battery through the 70 windings of relay 465, lower contacts of cam 405, inner right front contact of relay 498, conductor 318, right back contact of relay 392, commutator segment 395 to ground on brush 382. Relay 427 now energizes in a circuit which may be traced from 75 grounded battery through the right winding of relay 427, left contact of cam 404, upper right and lower left contacts of cam 405, to the same ground. The energization of relay 80 427 completes a circuit from grounded battery through the winding of the power magnet of sequence switch 400, lower right contact of cam 406, outer right front contact of relay 427 to ground at the upper right contact of cam 407, driving sequence switch 400, out of position 1 and into position 2. As sequence switch 400 leaves position 1, relays 427 and 465 release.

If at the time relay 425 is energized, the 85 sender finder switch is standing upon the terminals of an idle sender, relay 425 does not lock as previously stated and the circuit of stepping magnet 403 is immediately opened at the inner right contact of relay 90 425, preventing the advance of the brushes of the sender finder switch.

In position 2 of sequence switch 400, relay 425 reoperates in a circuit which may be traced from grounded battery through 100 the right winding of relay 425 to ground at the lower contacts of cam 408. Relay 494 then operates over an obvious circuit.

When the test line and the idle sender 105 have thus been found, battery and ground are connected to the ring and tip leads respectively. A circuit may then be traced from battery through the back contact of a relay in sender 430, conductor 486, brush arm 475 and its associated terminal, inner 110 left front contact of relay 494, lower right contact of cam 413, innermost left back contact of relay 392, brush 305, terminal 301, conductor 111, outer left front contact of relay 132, conductor 718, brush arms 715 115 and 705 and their associated first terminals, conductor 722, outer right back contact of relay 619, conductor 623, upper right contact of cam 830, conductor 831, winding of relay 621, and thence to ground over two parallel paths, one through the winding of relay 624, causing this relay to operate and the other over conductor 625, lower left contact of cam 832, conductor 833, inner right back contact of relay 619, 120 brush arms 706 and 716 and their associated first terminals, conductor 717, terminal 300 and brush 304, intermediate left back contact of relay 392, lower left contact of cam 412, brush arm 417 and its associated 125 130

terminal conductor 485, through the winding of the stepping relay or sender 430. Relay 621 is held energized in this circuit and sequence switch 800 is advanced out 5 of position 7 and into position 8 over a circuit which may be traced from grounded battery through the winding of the power magnet of sequence switch 800, upper left contact of cam 828, conductor 834, right 10 operated contact of relay 624 to ground.

Test of line finder.

The operation of the circuits above 15 described are tested in a manner now to be explained.

It should be noted that when sequence 20 switch 800 entered position 7 a circuit was completed from grounded battery through the winding of relay 607, conductor 626, upper left contact of cam 822, conductor 818 to ground at the outer left back contact of relay 14. Relay 607 energized in 25 this circuit and locked through its left front contact, contact of key 627, conductors 628 and 1215 to ground at the normal contact of key 5. Relay 607 prepares an energizing circuit for relay 610 through its right front contact, conductor 608 through the arc served by brush arm 1001 when 30 that master selector switch returns to normal.

Line finder non-start test.—In position 35 7 of sequence switch 800, a circuit may also be traced from grounded battery over two parallel paths one traced through the winding of relay 629, right back contact of relay 630 to conductor 631, and the other through the right winding of relay 399, conductor 1049, brush arms 1033, 1023 and 40 1003 and their associated terminals, conductor 723, inner right front contact of relay 621 to conductor 631 and thence to ground through the upper right and lower left contacts of cam 811, conductor 709, brush arms 45 702 and 712 and their associated first terminals, conductor 721, brush arm 1032 and its associated second terminal, conductor 1052, outer left front contact of relay 134, left back contact of relay 103 and the outer right 50 front contact of relay 102. Relays 629 and 399 are energized in this circuit. If the energization of relay 399 fails to start the line finder updrive magnet 316, an indication 55 of such condition will be given in the following manner. When interrupter 632 closes its contact for the first time, relay 633 is energized in a circuit which may be traced from ground at the left back contact of relay 630, left front contact of relay 629, contacts of interrupter 632, normal back contact of relay 634, winding of relay 633, conductor 635, upper right contact of cam 820 to grounded battery. Upon 60 energizing, relay 633 locks to ground at its front contact through the winding of 65

relay 643. When interrupter 632 opens its contacts, relay 634 is energized in series with relay 633. The energization of relay 634 completes a circuit which may be traced from grounded battery, winding of 70 relay 636, right back contact of relay 637, front contact of relay 634, contacts of interrupter 632 upon its next closure, left front contact of relay 629 to ground at the left normal contact of relay 630. Relay 75 636 upon operating, locks through its inner right front contact, conductors 1330 and 557, upper left contact of cam 817, conductor 818 to ground at the outer left back contact of relay 14. The operation of 80 relay 636 completes an obvious circuit for operating relay 619 and also closes a circuit from grounded battery through the winding of relay 1216, conductor 620 to ground at the outer right front contact of 85 relay 636. Relay 1216 is energized in this circuit. Lamp 638 is lighted in a circuit which may be traced from ground at the left front contact of relay 636 as an indication that the line finder relay 399 has 90 failed to start updrive magnet 316. The energization of relay 619 disconnects the tip, ring and sleeve conductors from the start circuit of Fig. 1, thus holding sequence 95 switch 800 in position 7. Relay 1216 upon 100 operating performs no useful function at this time. The test circuit will remain in this position until the time alarm circuit operates to give an indication that trouble 105 has been encountered. However, if the line 110 finder relay 399 starts the updrive magnet by closing a circuit therefor from grounded battery through to the winding of the updrive magnet 316, outer right armature and front contact of relay 399, commutator segment 395, brush 382 to ground. The energization of the updrive magnet 316 causes the line finder selector elevator to move upward as previously described. 115 When brush 381 makes contact with commutator segment 384 upon the subsequent upward movement of the line finder elevator, relay 103 energizes in a circuit from grounded battery through the winding and right normal contacts of relay 103, conductor 113, inner right normal contact of relay 398, right operated contact of relay 399, commutator segment 384, brush 381 to ground. The energization of relay 103 120 removes ground from conductor 1052, thus removing the short-circuit from around the winding of relay 630. This relay now operates in series with relay 629 to ground on conductor 1330 as previously traced.

The energization of relay 630 removes at 125 its left back contact, the short-circuit from the lower contact of interrupter 632, thus preventing the energization of relays 634, 633 and 636. The test is then permitted 130 to proceed.

Line finder over-step test.—In position 7 of sequence switch 800, with relay 621 energized, a test is made to determine whether the line finder oversteps. When 5 brush 381 engages commutator segment 384, a circuit may be traced from grounded battery, winding of relay 637, outer right back contact of relay 639, outer right front contact of relay 621, conductor 1047, brush 10 arms 1004 and 1024 and their associated 10 first terminals, brush arm 1034 and its associated second terminal, conductor 1050, right armature and front contact of relay 399, commutator segment 384, brush 381 15 to ground. Relay 637 is energized in this circuit, in turn closing an operating circuit for relay 640 through its outer left front contact. The energization of relay 640 prevents the energization of relay 641 and 20 the subsequent lighting of lamp 642. When relay 399 deenergizes, ground is removed from conductor 1050 and relay 639 then operates in series with relay 637 in a circuit which may be traced from grounded 25 battery through the windings of relays 637 and 639 in series, inner left front contact of relay 637, left normal contacts of relay 624, conductor 829, upper right contact of cam 817, conductor 818 to ground at the outer 30 left normal contact of relay 14. Upon the energization of relay 639, relay 640 is deenergized but since relay 640 is slow to release, sufficient time elapses before the energization 35 of relay 641 to permit the sender selector 403 to hunt over seven terminals and sequence switch 800 to advance out of position 7. Should the line finder overstep, the tip and ring conductors will not be connected through to the sender and as 40 a result relay 624 will not be operated, thus holding sequence switch 800 in position 7. Under this condition, relay 641 is energized in a circuit from grounded battery through the winding of relay 641, armature 45 and back contact of relay 640 inner right front contact of relay 639, left back contacts of relay 624 to ground on conductor 829 as previously traced. If, however, the line finder does not overstep, relay 633 will 50 be energized and relays 637, 639, 640 and 641, if operated, will be released. If, during the previously described operation, lamp 642 is lighted, it is an indication that the line finder has overstepped. If such condition exists, relay 619 will be energized 55 in a circuit which may be traced from grounded battery through the winding of this relay to ground at the right front contact of relay 641. The tip, ring and sleeve conductors are then disconnected at the back contacts of relay 619 from the test circuit. Sequence switch 800 will remain in position 7 until restored to normal by the operation of return-to-normal key 5.

Dialing three digit code.—It will be as-

sumed that the code number necessary to be dialled in order to cause the district circuit to select the test line terminals 455, 456 and 457 is 237. This code is transmitted in the manner to be described. With sequence 70 switch 800 in position 8, a circuit is in existence from ground at the outer left normal contact of relay 14, conductor 818, lower contact of cam 819, back contact of relay 851, lower contact of cam 853, winding of the power magnet of sequence switch 850 to grounded battery. Sequence switch 850 is advanced out of position 1 into position 2 over this circuit and is caused to make one complete revolution in a circuit 80 to ground at the upper contact of cam 853. As sequence switch 800 advances out of position 7, the tip and ring conductors of the group test line are closed through to the 100 ohm resistance 835. This circuit may 85 be traced from one side of resistance 835, lower contact of cam 854, conductor 836, upper contact of cam 837, conductor 833, inner right back contact of relay 619, brush arms 706 and 716 and their as- 90 sociated first terminals, conductor 717, line 95 finder contact 300, brush 304, intermediate left armature and back contact of relay 392, lower left contact of cam 412, sender selector brush arm 417 and its associated terminal, conductor 485, through the pulsing circuit in sender 430, conductor 486, brush arm 475 and its associated terminal, inner left front contact of relay 494, lower right contact of cam 413, innermost 100 left back contact of relay 392, line finder 105 brush 305 and contact 301, conductor 111, outer right front contact of relay 132, conductor 718, brush arms 715 and 705 and their associated first terminals, conductor 722, outer right back contact of relay 619, conductor 623, lower right contact of cam 830 to the other side of resistance 835. This circuit causes the sender 430 to be held until sequence switch 800 reaches position 8. As 110 sequence switch 850 rotates, this pulsing circuit just traced is intermittently interrupted at the lower contact of cam 854. These interruptions are two in number and continue until sequence switch 850 reaches 115 position 5½. At this time the circuit through cam 854 is shunted at the upper contact of cam 855, upper contact of cam 915, conductor 916, lower right contact of cam 832 to conductor 833. The interruptions of the impulses to the sender then ceases. Sequence switch 850, however, continues its rotation and as it enters position 120 16½, relay 851 is energized in a circuit which may be traced from grounded battery, winding of relay 851, contact of cam 856 to ground. Upon operating, relay 851 completes a locking circuit for itself through the winding of relay 852, through 125 its own front contacts, lower contact of 130

cam 819, conductor 818 to ground at the outer left back contact of relay 14. As sequence switch 850 leaves position 17, relay 852 is energized in series with relay 851. 5 Upon the energization of relay 852, a circuit may be traced from grounded battery through the winding of the power magnet of sequence switch 800, lower contact of cam 838 to ground at the front contact of 10 relay 852. Sequence switch 800 is advanced out of position 8 and into position 9 over this circuit. The operation of relay 851 prevents the energization of sequence switch 850 while sequence switch 800 is passing 15 from position 9 into position 9 by opening the energizing circuit for sequence switch 850 at its back contact. As sequence switch 800 leaves position 8, relays 851 and 852 deenergize. As sequence switch 800 enters 20 position 9 the energizing circuit for sequence switch 850 is again established from grounded battery through the winding of this sequence switch, lower contact of cam 853, normal contact of relay 851, lower contact of cam 819 to ground as previously 25 traced on conductor 818.

Sequence switch 850 now makes a second revolution during which the second digit, 3, of the three digit code is sent to sender 430 30 over the impulse circuit previously traced for sending the first digit. When sequence switch 850 reaches position 6 1/4 the interruptions through cam 854 are short-circuited over the lower contact of cam 857, 35 upper contact of cam 917, conductor 918, upper right contact of cam 832 to conductor 833. As sequence switch 850 enters position 16 1/2 on its second revolution, relay 851 again operates, performing the same 40 function as previously described for the first digit and relay 852 also energizes in series with relay 851, as before described, advancing sequence switch 800 into position 10. In position 10 of sequence switch 800, 45 relays 851 and 852 deenergize. With sequence switch 800 in position 10, a circuit is completed from grounded battery through the winding of relay 1201 conductor 1225, lower contact of cam 826, conductor 827 50 brush arms 1005 and 1025 and their associated first terminals, brush arm 1035 and its associated second terminal, conductor 1051, normal contacts of jack 366 to ground at the inner left front contact of relay 396. Relay 1201 energizes in this circuit and locks through its inner right front contact, outermost left back contact of relay 1216 to the same ground over conductor 827. 55 The operation of relay 1201 opens the energizing circuit for relay 501 and the circuit for advancing sequence switch 800 out of its normal position.

In position 10 of sequence switch 800 the 60 third digit of the three digit code is transmitted to the sender. Sequence switch 850

is caused to rotate a third time in a circuit through the lower contact of cam 853, normal contact of relay 851, lower left contact of cam 817 to ground on conductor 818. The pulsing circuit is then interrupted at 70 cam 854 a number of times equal to the digit to be sent, that is, seven, until the circuit is shunted through the lower contact of cam 858, upper contact of cam 919, conductor 921, upper left contact of cam 832 to 75 conductor 833. In position 16 1/2 of sequence switch 850 relay 851 operates as before and relay 852 is again energized in series with relay 851, advancing the sequence switch 800 out of position 10 over the circuit previously traced.

Transmission of one and two digits.

If it is desired to transmit only a one or two digit code to the sender this may be 85 done by transmitting the first digit in position 8 and causing the sequence switch 800 to advance thereafter from position 8 into position 11. In the case of two digits, the first two digits are transmitted in position 90 8 and 9 and upon completion thereof sequence switch 800 is advanced from position 9 to position 11.

Line closure tests.

These three digits transmitted over the pulsing circuit to the sender cause the sender registers A, B and C to take positions corresponding to the digits dialed. The sender then proceeds to make district brush and group selections in the manner fully described in Patent No. 1,395,977 and the sender line relay is held energized as sequence switch 800 advances into position 11 over the same circuit which was previously traced through resistance 835 in position 7 of sequence switch 800. In position 11 of sequence switch 800 relay 502 is energized from grounded battery through the winding of this relay, conductor 503, upper right contact of cam 822 to ground on conductor 818. The energization of relay 502 places ground on sleeve terminals 454 and 458 so that when the district reaches the position for trunk hunting, it is caused to pass over the first two sets of terminals and come to rest on the third set of terminals. The code transmitted to the sender is so translated therein that office selections are omitted and the fundamental circuit is closed through to 115 make trunk test. The closure of this circuit causes the energization of relay 504. The circuit for relay 504 may be traced from grounded battery through the winding of this relay, upper left contact of cam 839, 120 conductor 505, terminal 455 and brush 451, upper right and lower left contacts of cam 418, outer left front contact of relay 425, brush arm 424 and its associated terminal, conductor 483 over the fundamental cir- 125

cuit in the sender, conductor 484, brush arm 439 and its associated terminal, right contacts of cam 419, brush 452, terminal 456, conductor 506 to ground at the lower contact of cam 810. Relay 504 upon energizing completes a circuit for the energization of relay 507 from grounded battery through the winding of relay 507, left back contact of relay 508, front contacts of relay 504, conductors 1330 and 557, upper left contacts of cam 817 to ground on conductor 818. Relay 507 energizes and locks in series with the winding of relay 508 through its own front contact, conductor 508, outer right contact of cam 822 to ground on conductor 818. Sender 460 then advances into its talking selection position causing the de-energization of relay 504. Relay 508 energizes in series with relay 507 and connects ground at its right front contact, upper left contact of cam 840, conductor 509 to terminal 457 to render the test line busy. After the completion of talking selection in the sender, relay 504 again operates over the circuit previously traced and sequence switch 800 is advanced out of position 11 and into position 12 over a circuit which may be traced from grounded battery through the winding of the power magnet of sequence switch 800, upper left contact of cam 838, conductor 841, left front contact of relay 508, front contact of relay 504, conductors 1330 and 557, upper left contact of cam 817 to ground on conductor 818. As sequence switch 800 advances from position 11 the ground on sleeve conductor 509 is removed from the right front contact of relay 508 and is supplied from the inner left back contact of relay 510 through the upper right contact of cam 840 to conductor 509. Relays 507, 508 and 502 deenergize since their holding circuit is opened at the upper right contact of cam 822.

Test of polarized district supervisory relay.—With sequence switch 800 in position 12, the test of the district supervisory polarized relay 474 is made. A low resistance 511 of 20 ohms is first bridged across the tip and ring conductors for saturating the district supervisory relay 470. The circuit for this resistance may be traced from one side of resistance 511, right back contacts of relay 512, conductor 513, upper left contact of cam 842, lower left contact of cam 830, conductor 623, outer right back contacts of relay 619, conductor 722, brush arms 705 and 715 and their associated first terminals, conductor 718, outer right front contact of relay 132, line finder contact 301 and brush 305, left innermost back contact of relay 392, lower left contact of cam 413, brush arm 343 and its associated terminal winding of relay 470, lower left winding of repeating coil 436 to grounded battery. The other branch 60 of the circuit extends from the other side of

resistance 511, upper left contact of cam 837, conductor 833, inner right back contact of relay 619, brush arms 706 and 716 and their associated first terminals, conductor 717, line finder contact 300 and brush 304, intermediate left back contact of relay 392, lower right contacts of cam 412, brush arm 342 and its associated terminal, upper left winding of repeating coil 436 to ground. With sequence switch 800 in position 12, a circuit 75 may be traced from grounded battery, upper left contact of cam 820, winding of relay 514, left normal contacts of relay 514, to ground through interrupter 515. When interrupter 515 closes its upper contact, this 80 circuit will be completed and relay 514 will operate and lock to ground at its left front contact. A circuit may now be traced from grounded battery, upper left contact of cam 820 through the winding of relay 516, right 85 front contact of relay 514, lower contact of interrupter 515 to ground. When interrupter 515 closes its lower contact, relay 516 energizes and locks to ground at its inner right front contact. When interrupter 515 90 next closes its upper contact, relay 517 is energized in a circuit from grounded battery, winding of relay 517, left front contact of relay 516 to ground through the upper contact of interrupter 515. Relay 517 locks 95 through its right front contact and the inner right front contact of relay 516 to ground. The energization of relay 517 completes a circuit from grounded battery through the winding of the power magnet of sequence 100 switch 800, upper left contact of cam 828, conductor 834 to ground at the inner left front contact of relay 517. Sequence switch 800 is advanced from position 12 to position 14 in this circuit. As the sequence 105 switch advances out of position 12, relays 514, 516 and 517 deenergize. In position 14 of sequence switch 800 a circuit may be traced from grounded battery through the winding of relay 1226, conductor 1227, 110 upper right and lower left contacts of cam 922, conductor 923, lower right contact of cam 817 to ground on conductor 818. Relay 1226 energizes in this circuit and locks through its inner right front contact, conductor 1214 to ground at the lower right contact of cam 903. 115

It should be noted here that in position 12 of sequence switch 800, relay 518 was energized in a circuit from grounded battery 120 at the inner right back contact of relay 1228, conductor 1229, winding of relay 518, upper right contacts of cam 843 to ground. The energization of this relay completes a circuit from ground at its inner front contact, conductor 519, low resistance 845, lower right contact of cam 839, conductor 505, terminal 455, brush 451, upper contacts of cams 418, upper right winding of repeating coil 125 436, upper contact of cam 495, windings of the 130

polarized supervisory relay 474, upper left contact of cam 496, lower right winding of repeating coil 436, lower left and upper right contacts of cam 419, brush 452, terminal 456, conductor 506, upper right contact of cam 810, conductor 846, inner left back contact of relay 643 to battery at the outer front contact of relay 518. Relay 474 is energized in this circuit and advances the 10 district selector circuit to its "talking to operator" position in the well known manner. When sequence switch 800 advances out of position 12, relay 518 releases and in position 14 relay 520 is energized in a circuit from grounded battery, through variable resistance 521, winding of relay 520, outer normal contacts of relay 518, inner left back contact of relay 643, conductor 846, upper right contact of cam 810, conductor 506, terminal 456, brush 452, upper right contact of cam 413, innermost left back contact of relay 392, brush 305 and contact 301 of the line finder, outer right front contact of relay 132, conductor 718, brush arms 715 and 705 and their associated first terminals, conductor 722, outer right back contact of relay 619, conductor 623, lower left contact of cam 830, upper left contact of cam 842, conductor 813, right back contacts of relay 512, low resistance 511, upper left and lower right contacts of cam 837, conductor 1210 to ground at the upper left contact of cam 901. The energization of relay 520 completes a circuit from grounded battery, 35 interrupter 522, winding of relay 523, conductor 524, upper right contacts of cam 924, conductor 925, front contact of relay 520, conductor 525, upper contact of cam 926, conductor 927, upper right contact of cam 839, conductor 505, terminal 455, brush 451, upper right contact of cam 412, intermediate left back contact of relay 392, line finder brush 304, contact 300, conductor 717, brush arms 716 and 706 and their associated first 40 terminals, inner right back contact of relay 619, conductor 833, lower right contact of cam 837, conductor 1210, upper contact of cam 901 to ground. When interrupter 522 closes its contact, relay 523 is energized and locks to battery at its inner left front contact. Its energization also completes a circuit from grounded battery, lower left contact of cam 820, conductor 821, through the winding of relay 510, right back contacts of 45 relay 526, outer left front contact of relay 523, contact of interrupter 527, conductor 525, upper right contact of cam 926, conductor 927, upper right contact of cam 839, over conductor 505, through the district and line finder circuits as above traced to ground on cam 901. Relay 510 energizes as soon as interrupter 527 closes its contact and upon energizing locks to ground at its inner left front contact. By removing the ground from sleeve conductor 509 at its inner left

back contact it permits the district selector circuit to advance out of its "talking to operator" position in the well known manner. Relay 520 thereupon deenergizes, causing in turn the deenergization of relay 523. A circuit may then be traced from grounded battery, winding of the power magnet of sequence switch 800, upper right contact of cam 828, right back contact of relay 523, to ground at the intermediate front contact of 75 relay 510, for advancing this sequence switch out of position 14 into position 15. If the district selector circuit did not advance to its "talking to operator" position, relays 520, 523 and 510 would not have operated 80 and sequence switch 800 would have remained in position 14 until the operation of the time alarm circuit of Fig. 13.

Test of district supervisory relay.—As sequence switch 800 passes from position 14 85 to position 15, the circuit containing low resistance 511 for saturating the district supervisory relay 470 is held closed across the tip and ring sides of this circuit. With sequence switch 800 in position 15, relay 514 90 again operates when interrupter 515 closes its upper contact and when interrupter 515 opens its upper contact, relay 516 reoperates as above described. The energization of relay 516 in turn causes the energization of 95 relay 517 and also removes the short circuit around resistances 528, 529 and 530 and relay 531, bridging them in series with resistance 511 at its outer left front contact across the tip and ring sides of the group 100 test line. This increase in the resistance of the circuit through relay 470 causes the release of this relay and relay 531 energizes as soon as the district releases the line, (as described in the above mentioned Irvine 105 patent) permitting battery to be fed through the winding of relay 202 through the outer left back contact of relay 203, conductor 111, outer right front contact of relay 132 conductor 718, brush arms 715 and 705 and 110 their associated first terminals conductor 722, outer right back contact of relay 619, conductor 623, lower left contact of cam 830, lower right contact of cam 842, innermost 115 right front contact of relay 510, winding of relay 531, outer left front contact of relay 517, resistances 529, 528 and 511 in series, upper left contact of cam 837, conductor 833, inner right back contact of relay 619, brush arms 706 and 716 and their associated first 120 terminals, conductor 717, inner left back contact of relay 203 to ground. A circuit may now be traced from grounded battery through the winding of the power magnet of sequence switch 800, upper contact of cam 838, conductor 841, front contact of relay 531, upper contact of cam 819 to ground on conductor 818 for advancing this sequence switch out of position 15 and into position 125 16. In position 16 relays 514, 516, 517 and 130

531 deenergize and a circuit may be traced from ground on conductor 818, lower left contact of cam 822, conductor 847, outer right front contact of relay 1204, normal 5 contact of key 3, conductor 9, upper contact of cam 928 through the winding of the power magnet of sequence switch 900 to grounded battery, advancing this sequence switch out of position 2 and into position 3. As sequence switch 900 leaves position 2 lamp 908 10 is extinguished and lamp 912 is lighted in a circuit extending from grounded battery, lower left contact of cam 914 inner left back contact of relay 933, through lamp 912 to ground at the contact of key 902, indicating 15 that the second series of test are being made. A circuit may now be traced from ground, lower right contact of cam 848, conductor 849, lower right and upper left contacts of cam 922, conductors 929 and 841, upper contact of cam 838, winding of the power magnet of sequence switch 800 to grounded battery for advancing this sequence switch out of position 16 and into position 17. Sequence switch 800 is advanced into position 25 18 when the circuit is completed from grounded battery through the winding of the power magnet of sequence switch 800, upper left contact of cam 823, conductor 861 to ground at the inner left back contact of relay 1228. With sequence switch 900 in position 30 3, a circuit may be traced from grounded battery, through the winding of relay 1231, outer right back contact of relay 1228, outer right front contact of relay 1226, conductor 1232, left normal contact of relay 1316, conductor 1333, normal contacts of key 7, conductor 24, lower contacts of cam 930, conductor 931, inner left front contacts of relay 40 1204, conductor 1233, lower left contact of cam 805 to ground at the lower left contact of cam 806. Relay 1231 is energized in this circuit and completes a circuit from grounded battery, winding of the power magnet of sequence switch 800, lower left contact of cam 823 conductor 862, upper left back contact of relay 1228, innermost front contact of relay 1231, conductor 1234 to ground at the lower contact of cam 932 for 45 advancing this sequence switch out of position 18 and into position 1. The energization of relay 1231 connects ground from the lower contact of cam 903, conductor 1214, intermediate front contact of relay 1231, winding of relay 1228 through the winding of relay 1231 to grounded battery, causing relay 1228 to energize in series with relay 1231. 50

False revolution of district.—If relay 474 in the district circuit fails to release, district sequence switch 400 will rotate until relay 474 does release. Under such condition, ground will be removed from conductor 1051 in positions 18 $\frac{1}{4}$ to 11 $\frac{1}{2}$ of the district switch since relay 396 is released when the line finder selector is returned to normal by 55 the operation of down drive magnet 317. Relay 1201, whose holding circuit was traced to ground on conductor 1051, is of the slow to release type and will not release when this ground is removed under ordinary conditions. Therefore, as long as relay 1201 remains energized, sequence switch 800 will remain in position 1 until the district sequence switch stops its rotation or until the trouble alarm is sounded. If the district under test 70 is restored to normal, relay 1201 releases and sequence switch 800 is advanced to position 2 on its second revolution. The circuit for advancing this sequence switch to position 2 may be traced from battery through the winding of the power magnet of sequence switch 800, lower right contact of cam 801, conductor 802, left back contact of relay 1201, outermost right back contact of relay 1202, conductor 1203, operated contact of start key 1 to ground at the normal contact of key 2. 75

Test of district circuit with repeating coil in.—With sequence switch 800 in position 2 of its second revolution, a circuit may be traced from ground, outer right back contact of relay 803, conductor 804, left back contact of relay 601, inner left front contact of relay 602, conductor 1221, outer left back contact of relay 1207, conductor 825, upper right contact of cam 801, through the winding of the power magnet of sequence switch 800 to battery for advancing this sequence switch out of position 2 and into position 6. Sequence switch 800 then advances from position 6 to position 10, the test circuit performing the same functions in these positions as previously described for the same positions on the first revolution with the exception that the digit code sent to the sender is such as to cause the district circuit to stop in one of the talking positions which will include in the circuit repeating coil 436. This code will be assumed to be 100 159. 105

With sequence switch 800 in position 8, sequence switch 850 is caused to rotate on its first revolution over the same circuit as described for the first revolution of sequence switch 800. The pulsing circuit previously traced is interrupted at cam 854 to send impulses to the sender in the same manner until a shunt path around cam 854 is closed. This shunt path will be closed when sequence 110 switch 850 reaches position 4 $\frac{1}{4}$ and may be traced from cam 854, lower contact of cam 855, lower contact of cam 915, conductor 916, lower right contact of cam 832, conductor 833, upper left contact of cam 832, back to the lower contact of cam 854. In position 9 of sequence switch 800, cam 854 is shunted after five impulses have been sent in a circuit from cam 854, lower contact of cam 859, lower contact of cam 917, conductor 918, upper right contact of cam 832. 115 120 125 130

upper contact of cam 837, back to the lower contact of cam 854. In position 10 of sequence switch 800, cam 854 is short-circuited after nine impulses have been sent, that is, 5 when sequence switch 850 reaches position 14½ in a circuit which may be traced from cam 854, lower contact of cam 860, lower contact of cam 919, conductor 921, upper left contact of cam 832, upper contact of cam 837, back to the lower contact of cam 854. These impulses are registered in the sender and the district is then controlled in such a manner that when talking selection is made it will stop in one of the talking positions. 10

15 Sequence switch 800 then advances to position 11 in the manner previously described and resistance 835 is held bridged across the tip and ring to keep the sender line relay operated, thus holding the sender. Relay 504 then operates during trunk test as described for the first revolution and the party test is made by the district in the well known manner as described in application Serial No. 602,948. When the district selector circuit advances into its talking position, relay 504 reoperates and district relay 470 also energizes. Relays 502, 504, 508 and 507 function in the same manner as previously described for advancing sequence switch 800 20 into position 12. With sequence switch 800 in position 12, relay 470 is saturated in a circuit which includes low resistance 511. Relays 520 and 474 energize as before, the energization of relay 474 operating the proper message register. Relay 520 remains operated, relays 514, 516 and 517 operate under control of interrupter 515 causing the advance of sequence switch 800 to position 13 as 25 previously described and it advances to position under the control of cam 864 in the well known manner. As sequence switch 800 enters position 13, relay 512 energizes in a circuit which may be traced from grounded battery, upper left contact of cam 848, conductor 863, winding of relay 512, conductor 535, upper left contact of cam 914 to grounded battery. The energization of relay 512 in this circuit removes the shunt around resistances 528, 529 and 530 and relay 531, 30 but the latter does not operate. Supervisory relay 470 in the district releases, due to the high resistance connected in series across the line, but the district is not immediately released thereby, since it is held due to the energization of relay 490. In position 14 a circuit is completed from grounded battery, winding of relay 532, conductor 533, left contact of cam 924, conductor 925, front contact of relay 520, conductor 525, lower contact of cam 926, conductor 923, lower right contact of cam 817 to ground on conductor 818. Relay 532 is energized in this circuit and connects ground at its inner right front contact to the winding of relay 523 which 35 operates as soon as interrupter 522 closes its contact. Relay 532 also closes a shunt circuit at its outer right front contact around relay 531 and resistance 529. Supervisory relay 470 then reoperates over a condition which is similar to a low resistance subscriber's loop. The interval of time between the release of relay 470 in the district in position 13 of sequence switch 800 and its reoperation in position 14 of sequence switch 800 is such that the district circuit does not release, due to the slow release of relay 490. Relay 523 locks to battery at its inner left front contact and completes a circuit from grounded battery, lower left contact of cam 820, conductor 821, winding of relay 510, right back contact of relay 526, outer left front contact of relay 523, contact of interrupter 527, conductor 525, lower contact of cam 926, conductor 923, lower right contact of cam 817 to ground on conductor 818. When interrupter 527 closes its contact, relay 510 is energized and locks to ground at its inner left front contact. Relay 510 upon energizing completes a circuit from grounded battery, contact of interrupter 536, upper left front contact of relay 510, left back contact of relay 526, winding of relay 537, conductor 538 to ground at the lower contact of cam 933. When interrupter 536 closes its contact, relay 537 is energized, completing a circuit from grounded battery, winding of the power magnet of sequence switch 800, upper right contact of cam 823, conductor 539, right front contact of relay 523, outermost right front contact of relay 510, left front contact of relay 537, contact of interrupter 540 to ground. When interrupter 540 closes its contact, sequence switch 800 is advanced out of position 14 and into position 15. In position 15, a circuit may be traced from grounded battery, winding of the power magnet of sequence switch 800, upper contact of cam 838, conductor 841, outer right front contact of relay 537, upper contact of cam 819 to ground on conductor 818 for advancing this sequence switch out of position 15 and into position 16. In position 16, ground at the lower contact of cam 848, conductor 849, lower right and upper left contacts of cam 922, conductors 929 and 841, upper left contact of cam 838 through the winding of the power magnet of sequence switch 800 advances the sequence switch out of position 16 and into position 17. The holding circuit for district supervisory relay 470 is opened as sequence switch 800 advances out of position 15 and this relay de-energizes, allowing the district circuit to advance to its message register position. 40

45 In position 17, the district selector circuit has advanced to its message register position as previously stated, and a circuit may be traced from grounded battery, innermost right front contact of relay 465, left contacts of cam 481, conductor 409, inner right back

contact of relay 352, outer right normal contacts of relay 322, resistances 397, 390 and 394 in parallel, conductor 373, brush 307 and terminal 303, conductor 332, outer 5 back contact of relay 202, right back contact of relay 203, conductor 721, brush arms 712 and 702 and their associated first terminals, conductor 709, upper contacts of cam 865, conductor 866, inner right back contact of relay 934, conductor 936, outer left back contact of relay 644, outer left back contact of relay 645, left winding of relay 646 to ground. Relay 646 should energize in this circuit. It should be remembered, however, that the 10 battery from the district circuit was traced through resistances 397, 390 and 394. Relay 646 is so adjusted that if one or two of these resistances are open, it will not receive sufficient current to energize and, if they are 15 short-circuited, relay 937 will be energized through its right winding to ground. With relay 646 energized, a circuit may be traced from grounded battery, winding of relay 541, conductor 952, intermediate right back contact 20 of relay 643, inner right back contact of relay 644 to ground at the front contact of relay 646. Relay 541 energizes in this circuit and completes a circuit from grounded battery through its inner right front contact, 25 winding of relay 543, conductors 1330 and 557, upper left contact of cam 817 to ground on conductor 818 for energizing relay 543. Relay 543 locks to battery through its right front contact and when the district circuit 30 advances out of position 17, relay 646 releases, in turn releasing relay 541. Sequence switch 800 is then advanced into position 18 from grounded battery, winding of the power magnet of sequence switch 800, upper left 35 contact of cam 823, conductor 867, left front contact of relay 543, left back contact of relay 541, conductor 544 to ground at the right back contact of relay 937. If, however, relay 937 energizes due to the fact that one 40 of resistances 397, 390 and 394 is short-circuited, or if relay 646 fails to operate because of the open circuit condition of these resistances, sequence switch 800 will not advance out of position 17 but will remain 45 therein until the operation of the time alarm. When sequence switch 800 advances out of position 17, relays 510, 537, 532, 512 and 523 deenergize.

55 *Third revolution of test circuit.*

The test of the message register of the second party of the two party line will now be described. It will be remembered that in position 5, on the first revolution of sequence switch 800, relay 1307 energized with line finder selector switch 1030 standing on terminal 1 and that it locked through its innermost front contact to ground at the normal contact of key 5. When relay 1228 energized as sequence switch 800 entered upon

its second revolution, it completed a circuit from battery at its inner right front contact, conductor 1235, winding of relay 1316 to ground at the next to the inner front contact of relay 1307. As sequence switch 800 70 advances to position 18 on its second revolution, relay 933 is energized from grounded battery, winding of relay 933, outer left back contact of relay 934, conductor 935, left front contact of relay 1316, conductor 1333, normal contacts of key 7, conductor 24, lower contacts of cam 930, conductor 931, inner left front contact of relay 1204, conductor 1233, lower left contact of cam 805 to ground at the lower left contact of cam 806. Upon the energization of relay 933 in this circuit, a circuit may be traced from grounded battery through the winding of the power magnet of sequence switch 800, lower left contact of cam 823, conductor 862, outer left front contact of relay 933, right back contact of relay 939, conductor 940, intermediate back contact of relay 1213, brush arm 1312 and its associated terminal to ground, advancing this sequence switch out of position 18 and into position 1. Relay 933 locks in series with relay 934, in a circuit from ground at the upper right contact of cam 903, right front contact of relay 933, winding of relay 934, through the winding of relay 933 to grounded battery. Relay 934 is energized in this circuit.

The energization of relay 933 also opens the circuit through lamp 913 and completes a circuit through lamp 913 as an indication that the third series of tests are being made.

Sequence switch 800 is now caused to make a third revolution but sequence switch 900 remains in position 3. If the district circuit under test has not been opened by another line finder on its return to normal, ground is removed from conductor 1051 and relay 1201 releases, permitting sequence switch 800 to advance out of position 1 and into position 2. Positions 2 to 16 of the third revolution are passed through in a similar manner to those of the second revolution, the same three digit code being sent by sequence switch 850 in this revolution as in the previous one. When sequence switch 800 advances to position 11 on the third revolution, it waits until the district makes a party test as described in the above mentioned Irvine application Serial No. 602,948. Before making the party test, the district selector circuit connects battery from brush arm 342 and its associated terminal, lower right contact of cam 412, intermediate back contacts of relay 392, line finder brush 304 and terminal 300, conductor 717, brush arms 716 and 706 and their associated first terminals, inner right back contact of relay 619, conductor 833, lower left contact of cam 837, conductor 868, outer left back contact of relay 1236, conductor 1237, back contact of relay

938, inner left front contact of relay 934, winding of relay 939, upper left contact of cam 903 to ground. Relay 939 is energized in this circuit and at its right back contact 5 opens the energizing circuit for advancing sequence switch 800 out of position 18. As this sequence switch leaves position 17, relay 939 locks and relay 938 energizes from grounded battery, lower left contact of cam 10 942, left front contact of relay 939, normal contact of key 920, winding of relay 938, inner left front contact of relay 934, winding of relay 939, upper left contact of cam 903 to ground. Relay 938, upon energizing, 15 disconnects at its back contact the circuit which existed from conductor 717 brush arms 716 and 706 and their associated terminals, inner right back contact of relay 619, conductor 833, lower left contact of cam 837, conductor 20 868, outer left back contact of relay 1236, conductor 1237, back contact of relay 938, inner left front contact of relay 934, winding of relay 939 to ground at the upper left contact of cam 903. Conductor 1237 of this 25 circuit is connected through the front contact of relay 938, conductor 954 to battery at the right front contact of relay 502. When message registered current is again connected to the test line in position 17, relay 30 646 energizes over a circuit previously traced, in turn energizing relay 541 and relay 543 which causes sequence switch 800 to advance to position 18 as previously described. In position 18 of sequence switch 800 on its 35 third revolution, relay 1213 energizes in a circuit which may be traced from grounded battery, winding of relay 1213, outer right front contact of relay 1228, outer right front contact of relay 1226, conductor 1232, normal 40 contact of key 8, conductor 1247 outer left front contact of relay 934, conductor 935, left front contact of relay 1316, conductor 1333, normal contacts of key 7, conductor 24, lower contacts of cam 930, conductor 931, 45 inner left front contact of relay 1234, conductor 1233, lower left contacts of cams 805 and 806 to ground. A circuit may now be traced from grounded battery, winding of the power magnet of sequence switch 900, 50 lower right contact of cam 904, conductor 943, outermost front contact of relay 1213, innermost right front contact of relay 1213 to ground on cam 806 over the path previously described for advancing this sequence switch out of position 3 and into position 10 which is its next normal position. As sequence switch 900 returns to normal, relays 939, 938, 1226, 1213, 1228, 1230 and 1231 deenergize, in turn causing the de- 55 energization of relays 933 and 934. Lamps 913 and 909 are extinguished.

In position 18 of sequence switch 800, a circuit is completed from grounded battery, winding of relay 1029, brush arm 1022 and 60 its associated first terminal, conductor 1038,

right winding of relay 501, lower contacts of cam 806 to ground. Relays 1029 and 501 energize in this circuit. Sequence switch 900 is now advanced out of position 10 in a circuit which may be traced from grounded 70 battery, winding of the power magnet of sequence switch 900, lower left contact of cam 904, conductor 905, outermost front contact of relay 1307, outermost back contacts of relays 1306, 1305 and 1304, conductor 75 1330, upper left contact of cam 817 to ground on conductor 818. Sequence switch 900 advances into position 11 over this circuit. Lamps 908 and 909 are then relighted. With sequence switch 900 in position 11, a 80 circuit may be traced from grounded battery, winding of magnet 1030, normal contact of this magnet, outer front contact of relay 1029, conductor 1008, right contacts of cam 808, conductor 809, back contact of relay 609, inner right back contact of relay 610, conductor 611, normal contacts of keys 6, 3, 7, 8 and 2, conductor 12, outer right back contact of relay 1201, conductor 1206, intermediate normal contacts of relays 1304 and 85 1305, next to the inner normal contact of relay 1306, next to the inner operated contact of relay 1307, conductor 1332, upper left contact of cam 906, conductor 907, inner back contact of relay 1207, conductor 1218, 90 upper contact of cam 819 to ground on conductor 818. The energization of magnet 1030 in this circuit opens the short-circuit at its back contact from around relay 612 as previously mentioned, permitting this relay 95 to energize. Sequence switch 800 is then advanced out of position 18 and into position 1 over a circuit which may be traced through the front contact of relay 612. When sequence switch 800 leaves position 18, relays 1029, 612 and 501 and magnet 1030 deenergize, the latter stepping its associated switch to the next terminal. The circuit is now in condition to test the next district.

Class selector switch function.

It may be mentioned here that every time sequence switch 900 advances to positions 2, 5, 8, 11, 14 or 17, with sequence switch 800 in position 5, a circuit is closed from grounded 115 battery, winding of stepping magnet 1310, conductor 1334, upper right and lower left contacts of cam 945, conductor 946, inner left back contact of relay 1207, conductor 1238, normal contacts of keys 6 and 3, upper right contact of cam 848 to ground. Magnet 1310 is held energized while sequence switch 800 remains in position 5 and deenergizes when it is advanced out of this position. The brush assembly of the selector switch 120 associated with magnet 1310 is stepped to its next terminal. Every time brush arm 1341 engages a terminal it completes a circuit through a lamp from the ground over conductor 1012. These lamps are numbered 125 130

1 to 20, inclusive, and indicate which district selector is being tested. In this manner the selector follows the movement of the line finder connector and is able to change its 5 setting when stepped from terminal 21 and when the next line finder connector is used. When the brush assembly of the class selector switch reaches terminal 22 the holding circuit through relays 1307 and 1317 is 10 opened, permitting these relays to release. Sequence switch 900 is returned to normal in a circuit which may be traced from grounded battery through the winding of the power magnet of sequence switch 900, 15 lower right contact of cam 904, conductor 943, outermost normal contacts of relays 1307, 1306, 1305 and 1304, conductor 1330, upper left contact of cam 817 to ground on conductor 818.

20 *Stepping group connector.*

After all the district selectors associated with the first line finder switch have been tested, those connected with another line 25 finder switch are tested in the following manner. When the brush assembly of the line finder switch associated with magnet 1030 leaves its 21st terminal, relay 602, which, it will be remembered, is operated in a circuit 30 through brush 1031 to ground, releases and when relay 1201 deenergizes, sequence switch 800 is advanced out of position 1 and into position 2 over the circuit which was traced through the left back contact of this relay.

35 Relays 1019 and 1013 remain energized in a circuit from grounded battery, winding of relay 1027, brush arm 1026 and its associated first terminal, winding of relay 1019, right winding of relay 1013 to ground and relay 40 603 remains energized in the circuit which was traced over conductor 1037 to ground at the inner front contact of relay 1019. A circuit may then be traced from grounded battery through the winding of the power 45 magnet of sequence switch 800, upper right contact of cam 828, conductor 869, left front contact of relay 603, outer left back contact of relay 602, left back contact of relay 601, conductor 804 to ground at the right back contact of relay 803 for advancing this sequence 50 switch out of position 2 and into position 3. With sequence switch 800 in position 3, relay 1018 energizes in series with relay 605 in a circuit which may be traced from 55 grounded battery, winding of relay 1018, brush arm 1021 and its associated first terminal, brush arm 711 and its associated first terminal, conductor 724, brush arm 1002 and its associated first terminal, conductor 708, 60 right winding of relay 605, conductor 616, upper right contacts of cams 806 and 805, conductor 814, inner left back contact of relay 602, left back contact of relay 601, conductor 804 to ground at the right back contact of relay 803. Magnets 710 and 1020

then energize in a circuit from grounded battery, through the winding, armature and back contacts of these magnets in parallel, outer front contact of relay 1018, conductor 1008, right contacts of cam 808, conductor 809, normal contacts of relay 609, inner right back contact of relay 610, conductor 611, normal contacts of keys 6, 3, 7, 8 and 2 in series, conductor 12, outer right back contact of relay 1201, conductor 1206, intermediate back 70 contacts of relays 1304 and 1305, next to the inner back contacts of relays 1306 and 1307, conductor 1308 to ground at the upper left and lower right contacts of cam 810. Magnets 710 and 1020 are energized in this circuit. The energization of relay 1018 closes a short-circuit path around the winding of relay 612 as before described and upon the energization of magnets 710 and 1020 this short-circuit is opened and relay 612 is energized. Sequence switch 800 is then advanced from position 3 into position 4 over the same circuit previously traced through the front contact of relay 612. Magnets 710 and 1020 deenergize as before, 80 stepping the brush assemblies of the selector switches to their second terminals. A second line finder selector (not shown) is selected in the same manner as line finder 1030 was selected and the districts connected thereto 85 are tested in the same manner. Each line finder connector switch associated with a terminal of the group switch 1020 is picked up and its associated districts tested in turn.

90 *Stepping master connector.*

When the district selectors associated with line finder connector 1040 have been tested, the brush assembly of group selector 1020 is stepped to terminal 21. Relays 1019 and 1013 are held energized in a circuit from grounded battery, brush arm 1026 and its associated 21st terminal, winding of relay 1019, right winding of relay 1013 to ground. With sequence switch 800 in position 4, a 105 circuit may also be traced from grounded battery, winding of relay 614, conductor 647, brush arm 716 and its associated 21st terminal, brush arm 706 and its associated first terminal, inner right back contact of relay 619, conductor 833, lower right contact of cam 837, conductor 1210, upper left contact of cam 901 to ground. Relay 614 energizes 110 in this circuit. Relay 1018 now operates in a circuit from battery through its winding, brush arms 1021 and 711 and their associated twenty-first terminals, conductor 724, brush arm 1022 and its associated terminal conductor 1038, right winding of relay 501, lower right contact of cam 806, upper right contact of cam 805, conductor 814, inner left back contact of relay 602, left back contact of relay 601, conductor 804 to ground at the right back contact of relay 803. Magnets 710 and 1020 then energize in a circuit 120 125 130

traced from grounded battery through the winding armature and back contacts of these magnets in parallel, outer front contact of relay 1018, connector 1008, right contacts of cam 808, conductor 809, normal contacts of relay 609, inner right back contact of relay 610, conductor 611, normal contacts of keys 6, 3, 7, 8 and 2 in series, conductor 12, outer right back contact of relay 1201, conductor 1206, intermediate back contacts of relays 1304 and 1305, next to the inner back contacts of relays 1306 and 1307, conductor 1308 to ground at the upper left and lower right contacts of cam 810. Magnets 710 and 1020 are energized in this circuit. The energization of relay 1018 closes a short circuit path around the winding of relay 612 as before described and upon the energization of magnets 710 and 1020, this short circuit is opened and relay 612 is energized. A circuit now extends from grounded battery, through the winding of magnet 800, lower left contact of cam 801, conductor 813, outer right back contact of relay 1207, conductor 1208, front contacts of relays 612 and 614 to ground through the winding of relay 609, which operates. Magnet 800, however, does not operate because of the high resistance of relay 609. The operation of relay 609 opens at its back contact the energizing circuit of stepping magnets 710 and 1030 as just traced, causing these magnets to release, stepping their brush assemblies to their normal terminals. The release of these magnets reestablishes the shunt around relay 612, deenergizing it and causing the subsequent deenergization of relay 609. When the brush assembly of group switch 1020 steps off terminal 21, relays 1019 and 1013 deenergize, in turn deenergizing relay 603. The deenergization of relay 1019 completes a circuit from grounded battery through the winding of sequence switch power magnet 800, upper left contacts of cam 801, conductor 870, right back contact of relay 603, conductor 649 to ground at the outer back contact of relay 1019. Sequence switch 800 is rotated from position 4 to position 1, upon reaching which it is immediately advanced to position 2 to the operated condition of start key 1.

The deenergization of relay 603 completes a circuit from grounded battery, winding of relay 1007, brush arm 1001 and its associated first terminal, brush arm 701 and its associated first terminal, conductor 606, left winding of relay 605, conductor 807, upper left contact of cam 806, lower right contact of cam 805, conductor 604, left back contact of relay 603, outer left back contact of relay 602, left back contact of relay 601, conductor 804 to ground at the right back contact of relay 803. Relays 1007 and 605 energize in this circuit and a circuit is completed from grounded battery through the windings, armatures and back contacts of stepping magnets 700 and

1000, in parallel, right front contact of relay 1007, conductor 1008, right contacts of cam 808, conductor 809, back contact of relay 609, inner right back contact of relay 610, conductor 611, normal contact of keys 6, 3, 7, 8 and 2, in series, conductor 12, outer right back contact of relay 1201, conductor 1206, intermediate normal contacts of relays 1304 and 1305, next to the inner back contacts of relays 1306 and 1307, conductor 1308, upper left and lower right contacts of cam 810 to ground. When cams 700 and 1000 open their back contacts, the shunt circuit around relay 612, as previously described, is open and this relay energizes, advancing sequence switch 800 out of position 2 and into position 3. As sequence switch 800 leaves position 3, magnets 700 and 1000 deenergize, stepping their associated brush assemblies to the next terminal. The test will proceed in the same manner as previously described with the group connector associated with the second terminal as for that associated with the first terminal.

Conclusion of routine test.

It will be remembered that when sequence switch 800 entered position 7 at the beginning of a routine test, relay 607 was energized and remains locked through its left front contact to ground at the normal contact of key 5. When all the district selector circuits associated with the first master switch have been tested and the master switch steps from terminal 21 to normal, a circuit may be traced from ground through the winding of relay 610, right front contact of relay 607, conductor 608, brush arm 1001 and its associated normal terminal, winding of relay 1007 to grounded battery. Relays 610 and 1007 energize in this circuit. When relay 610 energizes, a circuit may be traced from ground through lamp 648, inner left front contact of relay 610, conductors 1017 and 1012 to ground at the contact of key 902. Lamp 648 is lighted as an indication that a cycle of tests has been completed. Relay 610 also opens at its inner right back contact an energizing circuit for stepping magnets 700 and 1000 and completes a circuit from grounded battery, lower left contact of cam 820, conductor 821, right back contact of relay 601, conductor 618, winding of relay 1209, conductor 1219, outer right front contact of relay 610 to ground. Relay 1209 is energized, in this circuit. A circuit may also be traced from grounded battery, winding of relay 1201, conductor 1225, outer left front contact of relay 610 to ground for energizing relay 1201. Relay 1209, upon energizing, locks through its inner left front contact, conductor 1239, lower right contact of cam 843 to ground. A circuit is completed from grounded battery, winding of the power magnet of sequence switch 800, lower

right contact of cam 823, conductor 824, right front contact of relay 1209, conductor 1210 to ground at the upper left contact of cam 901, advancing this sequence switch to position 18. Relay 1219 also completes a circuit from ground on its right front contact, conductor 15, left winding of relay 14, conductor 821 to grounded battery at the lower left contact of cam 820. The energization of relay 14 in this circuit closes an energizing circuit for relay 1216 from grounded battery, winding of relay 1216, conductor 1220 to ground at the right front contact of relay 14. Relay 619 is also energized from grounded battery, winding of relay 619, conductors 620 and 1220 to ground at the front contact of relay 14. The energization of relays 14 and 1216 removes ground from conductor 818, preventing the energization of all relays whose energizing circuit was traced to ground on conductor 818. Relays 14, 1216, 619 and 1209 deenergize as sequence switch 800 advances out of position 17. When sequence switch 800 reaches position 18, it is advanced to position 1 in a circuit from grounded battery, winding of the power magnet of sequence switch 800, upper left contact of cam 801, conductor 870, right back contact of relay 603, conductor 649 to ground at the outer back contact of relay 1019. The energization of relay 1201 holds sequence switch 800 in position 1. If it is not desired to perform another cycle of tests, key 5 is operated and key 1 is released. The operation of key 5 opens the locking circuit at its normal contacts, deenergizing all the relays which are held thereon. The release of relay 607 in turn causes the deenergization of relays 610, 1007 and 1201 and the circuit is restored to normal.

Return to normal key.

The operation of key 5 mentioned above returns the circuit to normal from any position in which sequence switch 800 may stand. The operation of key 5 releases relay 1301, if operated, restoring the time alarm circuit to normal, releases any of the operated class relays shown in Fig. 13, releases relays 1201 and 1211 and, as described above, energizes relays 14, 1216 and 619. Sequence switch 800 is advanced to position 1 over a circuit from grounded battery, winding of the sequence switch magnet, lower right contact of cam 828, conductor 871 to ground at the normal contact of key 1. With sequence switch 800 in position 1, a circuit may be traced from grounded battery, winding of relay 1007, brush arm 1001 and its associated terminal upon which it is standing at the time key 5 is operated, brush arm 701 and its associated terminal, conductor 606, right front contact of relay 1010, conductor 1054, operated contacts of key 5, conductor 25, back contact of relay 1240, conductor 1241, left winding of relay 501, upper left contact of cam 805, lower left contact of cam 806 to ground. Relays 1007 and 501 are energized in this circuit. A circuit may now be traced from grounded battery 70 through the windings of stepping magnets 700 and 1000 in parallel, inner left front contact of relay 1007, conductor 1009, lower right and upper left contacts of cam 811, conductor 812, winding of relay 612, front 75 contact of relay 501, conductor 613, upper left contact of cam 808, right back contact of relay 1240 to ground at the operated contacts of key 5. Magnets 700 and 1000 and stepping relay 612 energize in this circuit. 80 The energization of relay 612 completes a circuit from grounded battery, winding of relay 1240, conductor 1242, lower contacts of cam 865, conductor 813, outer right back contact of relay 1207, conductor 1208, front 85 contact of relay 612, back contact of relay 614, conductor 615, normal contacts of key 6, conductor 13, right back contact of relay 1209, conductor 1210 to ground at the upper left contact of cam 901. Relay 1240 energizes in this circuit, opening the circuit which was traced for stepping magnets 700 and 1000. These magnets upon deenergizing step the brush assemblies of their associated switches to the next terminal. The release of the stepping magnets short-circuits relay 612 at their back contacts, releasing this relay which in turn causes the deenergization of relay 1240. This process is repeated and the brush assemblies of the master switches are stepped from terminal to terminal until they reach their normal position at which time relay 1010 deenergizes, opening the circuit through relay 1007. 90 The release of relay 1010 also extinguishes 100 lamp 1011 as an indication that the master switch has been returned to normal. If a group selector is also off normal, a circuit may be traced from grounded battery, winding of relay 1018, brush arms 1021 and 711 110 and their associated terminals, conductor 724, outer left front contact of relay 1013, right back contact of relay 1010, conductor 1054, operated contact of key 5, conductor 25, left back contact of relay 1240, conductor 1241, left winding of relay 501, upper left contact of cam 805 to ground at the lower left contact of cam 806. The energization of relays 1018 and 501 completes a circuit from grounded battery through the windings of magnets 710 and 1020, inner front contact of relay 1018, conductor 1009, lower right and upper left contacts of cam 811, conductor 812, winding of relay 612, front 115 contact of relay 501, conductor 613, upper left contact of cam 808, right back contact of relay 1240 to ground at the operated contact of key 5. The operation above described for stepping the master switch to normal is 120 repeated here and group switches 710 and 125 130

1020 are stepped to normal. When brush arm 1026 reaches its normal terminal, relays 1019 and 1013 deenergize, extinguishing lamp 1016 as an indication that the group 5 switch has been restored to normal. If line finder selector 1030 is also off normal at this time, the deenergization of relay 1027, due to the fact that the group switch has been restored to normal, completes a circuit from 10 grounded battery, winding and back contact of magnet 1030, left back contact of relay 1027, brush arm 1036 and its associated terminal to ground. Magnet 1030 interrupts its own circuit, stepping the associated brush assembly to normal. When brush arm 1036 engages its normal terminals the circuit through magnet 1030 is opened. As soon as all the selector and connector switches have returned to normal, key 15 20 5 is restored to its normal position.

Master and group switch spare terminals.—If there are any spare terminals on the arcs of the master selector switch, those in the arc served by brush arm 706 will be 25 connected to conductor 647, those in the arc of brush arm 1002 will be connected to conductor 606 and those in the arc of brush arm 1006 over conductor 1039, through resistance 1055 to ground. Resistance 1055 is equal in 30 value to the resistance of the left winding of relay 1013 and provides a holding path for relay 1010 so that lamp 1011 may be kept lighted as a master switch off-normal signal. When the brush assemblies of the master 35 switch steps to a group of spare terminals, sequence switch 800 is in position 3 and relay 614 energizes in a circuit extending from battery through its winding, conductor 647, brush arm 706 and the associated spare terminal conductor 658 inner right back contact of relay 619, conductor 833, lower right contact of cam 837, conductor 1210 to ground at the upper contact of cam 901. The energizing circuit for sequence switch 40 magnet 800 is opened at the back contact of relay 614, preventing its advance until a connected terminal is encountered. A circuit may now be traced from battery through the winding of relay 1007, brush arms 1001 and 50 701 and their associated terminals, conductor 606, brush arm 1002 and its associated terminal, conductor 708, right winding of relay 605, conductor 616, upper right contacts of cams 806 and 805, conductor 814, inner left back contact of relay 602, left back contact of relay 601, conductor 804 to ground at the right back contact of relay 803.

Relays 1007 and 605 energize in this circuit and stepping magnets 700 and 1000 55 operate in a circuit which may be traced through the windings, armatures and back contacts of these magnets in parallel, right front contact of relay 1007, conductor 1008, right contacts of cam 808, conductor 809, back contact of relay 609, inner right back

contact of relay 610, conductor 611, normal contacts of keys 6, 3, 7, 8 and 2 in series, conductor 12, outer right back contact of relay 1201, conductor 1206, intermediate normal contacts of relays 1304 and 1305, 70 next to the inner back contacts of relays 1306 and 1307, conductor 1308 to ground at the upper left and lower right contacts of cam 810. The master magnets 700 and 1000 energize, in turn causing energization of relay 612 in the manner formerly explained. Relay 609 then energizes in a circuit extending through its winding, front contacts of relays 614 and 612, conductor 1208, outer right back contact of relay 1207, conductor 80 813, lower left contact of cam 801, through the winding of magnet 800 to grounded battery. Magnet 800 does not energize due to the high resistance of relay 609 in this circuit. Relay 609 opens the circuit for 85 magnets 700 and 1000, causing their release and as a result stepping their brush assemblies to the next terminal. If this terminal also is spare, the same process is repeated until a connected terminal is reached. 90

The group switch is stepped over a spare terminal in a manner similar to that described for stepping this switch off terminal 21 and it will not be described in detail here. With the previous description in mind and 95 considering conductors 647 connected to the spare terminal of arc 716, 1056 to the spare terminal of arc 1022 and 1057 to the spare terminal of arc 1026, the circuits involved become obvious. 100

Time measure alarm feature.—It will be remembered that when a routine test is made, the operation of key 1 completed a circuit from grounded battery, winding of relay 1301, brush arm 1302 and its associated normal contact, conductor 1303 to ground at the operated contact of key 1. Relay 1301, upon energizing, locks through its right front contact, contact of key 1309, conductor 23, normal contact of key 5, conductor 1230, inner left normal contacts of relay 1226, conductor 844 to ground at the lower left contact of cam 843. Relay 1301 therefore remains energized while sequence switch 800 makes a complete revolution. 110 The energization of relay 1301 completes a circuit from ground, contact of interrupter 1318, inner left front contact of relay 1301, brush arm 1322 and its associated terminal, winding of stepping magnet 1320 to battery. 115 Each time interrupter 1318 closes its contact, stepping magnet 1320 energizes and when the interrupter opens its contact, the magnet releases, stepping its associated brush assembly one terminal. This process is repeated as long as relay 1301 remains energized. Should trouble develop in either the test circuit or the district circuit under test, or should sufficient time not be left after the completion of a circuit to permit the 120 125 130

completion of a test, brush 1323 will have reached terminal 16 before relay 1301 is deenergized. A circuit then may be traced from grounded battery, winding of relay 1324, lamp 1319, brush arm 1323 and its associated 16th terminal to ground at the outer left front contact of relay 1301. Lamp 1319 is lighted and alarm 1325 rings as an indication of trouble in the circuit. Since only the first fifteen terminals of the arc served by brush 1323 are connected to interrupter 1318, the brush assembly will remain on terminal 16 until the operation of key 1309. Relay 1301 then deenergizes, completing a circuit from ground at its outer left back contact, brush arm 1321 and its associated terminals, back contact and winding of magnet 1320 to grounded battery. Magnet 1320 interrupts its own circuit, stepping its associated brush assembly to normal.

End of cycle key.—When the master connector switches were stepped from terminal 21 to normal after all the districts had been tested, relays 1007 and 610 were energized in series as previously described. If now a second cycle of routine tests is desired this may be accomplished by the operation of end of cycle key 627. The operation of this key opens the holding circuit through relay 607 causing this relay to deenergize. The deenergization of this relay opens the circuit of relays 610 and 1007. The deenergization of relay 610 opens the energizing circuit of relay 1201 at its outer left front contact. Relay 1201 deenergizes, permitting sequence switch 800 to advance out of position 1 and into position 2, thus starting the second cycle of routine tests.

Control advance key.—If, as previously noted, the lamp 1319 lights or alarm 1325 is sounded, trouble may be corrected by operating control advance key 2 shown in Fig. 11. The operation of this key completes a circuit from ground at its operated contact, left winding of relay 14, conductor 821, lower contact of cam 820 to grounded battery. Relay 14 is energized in this circuit. A circuit is also completed from grounded battery, winding of the power magnet of sequence switch 800, lower right contact of cam 823, conductor 824 to ground at the operated contact of key 2. Sequence switch 800 is advanced out of the position in which it has come to rest and into position 18. The operation of key 2 also opens at its back contacts a circuit for advancing sequence switch 800 out of position 1 and the circuit for operating magnet 1030. The energization of relay 14 completes at its outer left front contact an obvious circuit for lamp 16. Relay 14 also completes a circuit from grounded battery, winding of relay 619, conductor 620 and 1220 to ground at the right front contact of relay 14. The

energization of relay 619 opens the tip, ring and sleeve conductors, permitting the district circuit to release. Relay 1216 is also operated to the same ground at the right front contact of relay 14 over conductor 1220. Relay 1201 then deenergizes since its holding circuit has been opened at the outermost left back contact of relay 1216. If the trouble has occurred on the first revolution of sequence switch 800, this sequence switch will advance to position 1 over a circuit from grounded battery, winding of the sequence switch magnet, lower left contact of cam 823, conductor 862, outer left front contact of relay 933, right back contact of relay 939, conductor 940, intermediate back contact of relay 1213, brush arm 1312 and its associated terminal to ground. If the trouble appears on any other revolution, the switch will remain in position 18 until key 2 is restored to normal. The release of this key causes the routine test to proceed in the usual manner.

Plurality of group selectors off normal.

If two group switches step off normal at the same time, two relays similar to relay 1013 will be energized and a circuit may then be traced from grounded battery through two resistances such as resistance 1015 in parallel, conductor 1014, intermediate back contact of relay 1202, winding of relay 1211, conductor 1212 to ground at the normal contact of key 5. Relay 1211 is so adjusted that it will not operate when one resistance such as 1015 is connected in series with it. However, if two or more resistances are connected in parallel in this circuit, this relay operates, locking through its left front contact to battery through the winding of relay 1202. Relay 1202 is energized in this circuit. The energization of relay 1211 also completes an obvious circuit for lamp 1243 which lights as an indication that more than two group selectors are off normal. Relay 1202, upon energizing, locks through its right front contact to ground at the normal contact of key 5. Sequence switch 800 is then advanced to position 1 over a circuit from ground through the left front contact of relay 1202, conductor 871, lower right contact of cam 828, winding of magnet 800 to battery. Relay 1202 also opens at its outermost right back contact the circuit for advancing sequence switch 800 out of position 1 and opens at its intermediate back contact the energizing circuit for relay 1211. Relay 1211 releases and lamp 1243 remains lighted in a circuit through the outermost right front contact of relay 1202, conductor 1203, operated contact of key 1 to ground at the normal contact of key 2. Under this condition the test may be continued by first restoring the

circuit to normal by the operation of key 5.

False charge test.—A test may be made on the district circuit for calls which are not to be charged. This is accomplished by the 5 operation of key 920 at the beginning of the test. The operation of the circuit during the first revolution and up to position 14 of the second revolution of sequence switch 800 is the same as for the ordinary test. When 10 sequence switch 800 enters position 14 on its second revolution, relay 532 is energized in a circuit which may be traced from grounded battery, winding of relay 532, conductor 533, left contact of cam 924, conductor 925, front 15 contact of relay 520, which is in its operated condition, conductor 525, lower contact of cam 926, conductor 923, lower right contact of cam 817 to ground on conductor 818. The energization of relay 532 completes a 20 circuit from grounded battery, windings of relays 643 and 526 in parallel, conductor 650, outer right back contact of relay 934, operated contact of key 920, conductor 947 to ground at the outer left front contact of relay 532. Relay 526 upon energizing, opens at its right back contact the energizing circuit for relay 510, thus holding sequence switch 800 in position 14. Relay 532 upon energizing, completes a circuit for the energization of relay 523 when interrupter 522 25 closes its contact. Relay 523 locks to battery at its inner left front contact. A circuit may now be traced from grounded battery, right winding of relay 545, winding of relay 546, right back contact of relay 545, right front contact of relay 526, outer left front contact of relay 523, contact of interrupter 527, conductor 525, lower contact of cam 926, conductor 923, lower right contact of cam 30 35 40 45 50 55 60 65 70 75 80 85 90 95 100 105 110 115 120 125 817 to ground on conductor 818. When interrupter 527 closes its contact, relay 546 is energized. When interrupter 527 opens relay 545 energizes. Relay 546 is held energized through the left winding of relay 545, innermost front contact of relay 546, conductor 557, upper left contact of cam 817 to ground on conductor 818. When the interrupter 527 again closes, relay 546 deenergizes. The release of relay 546 completes a circuit from grounded battery, lower contact of cam 820, conductor 821, winding of relay 510, inner left front contact of relay 545 to ground at the intermediate back contact of relay 546. Relay 510 energizes in this circuit and locks to ground at its inner left front contact. When interrupter 527 opens its contact relay 545 deenergizes. The next closure of the interrupter causes the operation of relay 546 and the following opening of the interrupter operates relay 545. A circuit may now be traced from grounded battery, interrupter 536, outer left front contact of relay 510, left front contact of relay 526, front contacts of relays 546 and 545, winding

of relay 537, conductor 538, lower contact of cam 932 to ground. A circuit is now in existence from grounded battery, winding of the power magnet of sequence switch 800, upper right contact of cam 823, conductor 539, right front contact of relay 523, outermost right front contact of relay 510, left front contact of relay 537, contact of interrupter 540 to ground. When interrupter 540 closes its contact, sequence switch 800 is advanced out of position 14 and into position 15. The sequence switch is advanced to position 16 in a circuit which may be traced from battery through the winding of the power magnet, upper contact of cam 838, conductor 841, outer right front contact of relay 537, conductor 1218, upper contact of cam 819 to ground on conductor 818. When sequence switch 800 reaches position 16 it is immediately advanced to position 17 in a circuit traceable from ground, lower contact of cam 848, conductor 849, lower right and upper left contacts of cam 922, conductors 929 and 841, upper contact of cam 838, winding of power magnet 800 to battery.

While sequence switch 800 remained in position 14 and with relay 643 operated, a circuit was traced from grounded battery, winding of relay 645, outer left front contact of relay 643, conductor 1225, inner right front contact of relay 1201, outermost left back contact of relay 1216, conductor 827, brush arms 1005, 1025 and 1035 and their associated terminals to ground on conductor 1051 for operating relay 645. Relay 520 is held energized in a circuit to ground at the inner left front contact of relay 643. Relay 643 also completes a circuit from grounded battery, resistance 651, innermost right front contact of relay 643, conductor 846, upper right contact of cam 810, conductor 506, terminal 456, brush 452, upper right and lower left contacts of cam 419, lower right winding of repeating coil 436, contacts of cam 496, winding of relay 474, contacts of cam 495, upper right winding of repeating coil 436, upper contacts of cam 418, brush 451, terminal 455, conductor 505, upper right contact of cam 839, conductor 927, contacts of cam 948, outer front contact of relay 645 through the contact of interrupter 652 to ground. If district supervisory relay 474 is properly adjusted, it will energize and deenergize with the closing and opening of the contacts of interrupter 652. The time interval of interrupter 652 is not sufficient to charge the call. As sequence switch 800 leaves position 15, the district circuit is released and when the district circuit returns to normal, ground is removed from conductor 1051, deenergizing relay 645. The deenergization of relay 645 completes a circuit from grounded battery, winding of the power magnet of sequence switch 800, upper left contact of cam

823, conductor 867, left back contact of relay 548, conductor 549, outermost right front contact of relay 643, inner right back contact of relay 645, conductor 653, upper left contact of cam 903 to ground for advancing the sequence switch out of position 17 and into position 18. As the sequence switch leaves position 17, relay 532 deenergizes, in turn deenergizing relays 643, 526, 545 and 546.

10 *False charge.*

If, under the conditions explained in the preceding paragraph, district supervisory relay 474 fails to release when interrupter relay 652 opens its contact, the call will be charged and consequently the district selector will stop in its message register position 16 and register the call. Under this condition relay 654 is energized in position 17 of sequence switch 800 in a circuit which may be traced from ground through the winding of relay 654, outer left front contact of relay 645, outer left back contact of relay 644, conductor 936, inner right back contact of relay 934, inner left front contact of relay 645, conductor 709, brush arms 702 and 712 and their associated terminals, conductor 721, right back contact of relay 203, outer back contact of relay 202, conductor 332, terminal 303, brush 307, resistances 397, 390 and 394 in parallel, outer right normal contacts of relay 322, inner right back contact of relay 352, left contacts of cam 481 to battery at the innermost right contact of relay 465. The energization of relay 654 completes a circuit for energizing relay 548. This circuit may be traced from grounded battery, winding of relay 548, left back contact of relay 547, conductor 550, right intermediate operated contacts of relay 643, inner right back contact of relay 644 to ground at the front contact of relay 654. When the district circuit advances out of position 16 $\frac{1}{4}$, relay 465 deenergizes, removing the battery on conductor 721. Relay 548 then locks in series with relay 547, causing the energization of the latter, in a circuit from grounded battery, through the windings of relays 548 and 547 in series, right front contact of relay 548, conductors 1330 and 557, upper left contact of cam 817 to ground on conductor 818. The energization of relays 548 and 547 opens a circuit over conductor 867 for advancing sequence switch 800 out of position 17, holding this sequence switch in that position. Relay 547 completes an obvious circuit for lighting lamp 551. Relays 1216 and 619 are energized in parallel over conductor 620 to ground at the inner right front contact of relay 547. Relay 619 upon operating opens the tip, ring and sleeve conductors, releasing the associated line. The energization of relay 1216 opens the holding circuits for relays 1201 and 645

and these relays release. Sequence switch 800 remains in position 17 and lamp 551 remains lighted until the operation of the time alarm circuit.

70 *False ground 2d party.*

A false ground test is made of the second party of the two party district during the third revolution of sequence switch 800. When sequence switch 800 reaches position 11 relay 939 is energized and the tip conductor causes the district circuit to set up a charged condition for the second party. When sequence switch 800 arrives in position 17 district sequence switch 400 will be 80 in position 16 and relay 939 will be again operated over conductor 717. This circuit may be traced from grounded battery, winding of relay 349, brush arm 342 and its associated terminal, lower right contact of 85 cam 412, intermediate back contact of relay 392, line finder brush 304, terminal 300, conductor 717, brush arms 716 and 706 and their associated terminals, conductor 658 inner right back contact of relay 619, conductor 833, lower left contact of cam 837, conductor 868, upper left back contact of 90 relay 1236, conductor 1237, back contact of relay 938, inner left front contact of relay 934, winding of relay 939, upper left contact of cam 903 to ground. The energization of relay 349 in this circuit operates relay 352 in a circuit from grounded battery, right winding of relay 352, outer left front contact of relay 324 to ground at the front contact of relay 349. The energization of relay 352 prevents the party selector switch from advancing until relay 352 releases. In position 14 of the third revolution of 100 sequence switch 800 a circuit may be traced from grounded battery, winding of relay 644, conductor 655, outer right operated contacts of relay 934, operated contact of key 920, conductor 947 to ground at the upper left front contact of relay 532. Relays 644 and 532 remain energized until sequence switch 800 leaves position 17. With relays 939 and 644 energized, a circuit may be traced from grounded battery, 110 inner left front contact of relay 644, conductor 656, winding of relay 1244, inner normal contacts of relay 1244, conductor 1245, outer right front contact of relay 644, conductor 657, upper contact of interrupter 1246, operated contact of key 920, right front contact of relay 939, conductor 940, back contact of relay 1213, brush arm 1312 and its associated terminal to ground. Relay 1244 operates when the upper contact of interrupter 1246 closes and locks to ground at its inner right front contact. A circuit may be traced from grounded battery, winding of relay 1236, outer front contact of relay 1244, lower contact of interrupter 1246 120 to ground over the path previously traced. 130

Relay 1236 is energized when interrupter 1246 closes its lower contact and locks through its right front contact, conductor 847, lower left contact of cam 822 to ground 5 on conductor 818. The energization of relay 1236 opens the energizing circuit of relay 939 causing this relay and relays 349 and 352 in the district circuit to release. Relay 1236 also connects a short-circuit 10 around the winding of relay 644, deenergizing this relay. The party test switch in the district circuit now advances in the well known manner performing its functions as described in the above mentioned Irvine application. Message register current from 15 the right front contact of relay 465 is connected then to conductor 720 causing the energization of relay 646 as hereinbefore described. If when relay 644 was energized 20 the district failed to recognize the false ground and registered over conductor 720, relay 654 operates in a circuit from ground through the winding of relay 654, outer left front contact of relay 644, conductor 936, 25 inner right front contact of relay 934, conductor 949, brush arms 703 and 713 and their associated terminals, conductor 720, right front contact of relay 203, upper back contact of relay 202, conductor 332, terminal 303, brush 307, resistances 397, 390 and 394, outer right normal contacts of relay 322, inner right back contact of relay 352, left contacts of cam 481, innermost right front contact of relay 465 to grounded battery. Relays 548 and 547 energize and 30 perform their functions as previously described. If the district under test does not recognize the false ground on the tip conductor in position 11 of sequence switch 800 and fails to set the district for charging over conductor 720 and for the same reason did not recognize it for retest, the charging current is sent over conductor 721. Under this condition no relays are operated, and 35 sequence switch 800 halts in position 17.

Coin districts.

If coin district selector circuits are being tested, the current to the district supervisory relay, similar to relay 474, is interrupted in the same manner as described for the message register district selector. Upon making coin test, relay 953 is operated in a circuit which may be traced from positive battery from sender 430, conductor 486 brush arm 475 and its associated terminal, inner left front contact of relay 494, left front contact of relay 465, lower right contact of cam 412, left intermediate back contact of relay 392, brush 304, terminal 300, conductor 717, brush arms 716 and 706 and their associated terminals, inner right back contact of relay 619, conductor 833, lower left contact of cam 837, conductor 868, outer left back contact of relay 1236, conductor

1237, winding of relay 953, conductor 951, next to the outer front contact of relay 1306, which, it will be remembered, is operated when coin type circuits are being tested, conductors 1329 and 1215 to ground at the 70 normal contact of key 5. District relay 474 then functions properly as previously described and sequence switch 800 is advanced out of position 17 in this manner. Relay 541 is energized in a circuit traced from 75 battery, through its winding, conductor 952, right intermediate back contact of relay 643, inner right back contact of relay 644, to ground at the front contact of relay 953. Relay 541 connects battery through its 80 right front contact to the winding of relay 543, conductor 1330, upper left contact of cam 817 to ground on conductor 818, energizing relay 543 which locks to battery through its own right front contact. 85

When coin collect current is removed from conductor 717, relay 953 releases, in turn releasing relay 541. Sequence switch 800 then advances out of position 17 into position 18 in a circuit extending from battery through the magnet 800, upper left contact of cam 823, conductor 867, left front contact of relay 543, left back contact of relay 541, conductor 544, to ground at the right back contact of relay 937. 95

If, with key 920 operated as described under the test for false charge, the charge relay 465 in the district fails to hold, negative coin current will be connected from the sender to conductor 717 as previously traced to conductor 868, outer left back contact of relay 1236, conductor 1237, operated contact of key 920, winding of relay 950 to ground as traced on conductor 951.

Relay 950 energizes and the current for 105 operating relay 541 extends over conductor 952 to ground at the operated contact of relay 950. The test circuit is then advanced as already recounted.

Test of particular circuit.—If it is desired to test a particular district selector circuit out of all the district selector circuits accessible for test, keys 6 and 1 are operated in the order named. Key 6 is operated before key 1 so that the test circuit will not 115 start a routine test upon the operation of key 1. The operation of key 1 advances sequence switch 800 to position 2 in the well-known manner. The operation of key 6 opens the local circuits that advance sequence switch 800 out of positions 2, 3, 4 and 5, and for operating the selector magnets, as previously described. It also provides a circuit for operating the selector magnets under control of the dial as will be 120 further described and completes a circuit from grounded battery, winding of relay 872, upper normal contacts of dial 873, conductor 874, operated contacts of key 6, conductor 13, right back contact of relay 1209, 125 130

conductor 1210, upper contact of cam 901 to ground. Relay 872 energizes in this circuit and relay 601 is energized in a circuit which may be traced from grounded battery, winding of relay 601, conductor 874 to ground, as previously traced. With sequence switch 800 in position 2, the dial 873 is operated in the usual manner of operating dials to transmit the code number of the desired district circuit. Relay 1007 is operated in a circuit from grounded battery, winding of relay 1007, brush arm 1001, and its associated normal terminal, conductor 608, right back contact of relay 607, conductor 707, brush arm 701 and its associated normal terminal, conductor 606, left winding of relay 605, conductor 807, upper left contact of cam 806, lower right contact of cam 805, conductor 604, left back contact of relay 603, outer left and inner left back contacts of relay 602, left front contact of relay 601, conductor 804 to ground at the right back contact of relay 803. Upon each opening of the circuit due to the operation of dial 873, relay 601 deenergizes in turn causing the deenergization of relay 1007. Stepping magnets 700 and 1000 are further energized and deenergized in unison with relay 1007 causing their corresponding brush assemblies to be stepped a number of terminals corresponding to the number of impulses in the first digit dialed. After the operation of the dial to transmit the first digit, key 875 is operated. A circuit may now be traced from grounded battery, winding of relay 876, left back contact of relay 803, operated contacts of key 875, left front contact of relay 872, conductor 877, operated contact of key 6, normal contacts of keys 3, 7, 8 and 2, conductor 12, outer right back contact of relay 1201, conductor 1206, intermediate back contacts of relays 1304 and 1305, next to the inner back contacts of relays 1306 and 1307, conductor 1308, upper left and lower right contacts of cam 810 to ground. Relay 876 energizes in this circuit, and when key 875 is released relays 876 and 803 are energized in series to the same ground, at the front contact of relay 876. Sequence switch 800 is now advanced out of position 2 into position 3 over a circuit from grounded battery winding of the power magnet of sequence switch 800, lower left contact of cam 801 to ground at the right front contact of relay 803. As sequence switch 800 reaches position 2, relays 803 and 876 deenergize. In position 3, the group selector is stepped to the desired terminal by the operation of dial 873, and in this position relay 1018 energizes from grounded battery, winding of relay 1018, brush arm 1021 and its associated normal terminal, brush arm 711 and its associated normal terminal, conductor 724, brush arm 1002 and its associated terminal, conductor 708, right winding of relay 605, conductor 616, upper right contacts of cams 806 and 805, conductor 814, left front contact of relay 601, conductor 804 to ground at the right back contact of relay 803. Stepping magnets 710 and 1020 energize and deenergize in synchronism with relay 1018 which is controlled by the operation and release of relay 601 which, in turn, is controlled, as before described, by the contacts of dial 873. When the group switch has reached the desired terminal, key 875 is again operated, operating relays 876 and 803 and advancing sequence switch 800 to position 4. In position 4, dial 873 is operated to send one impulse, stepping the desired line finder one terminal in order to make a class setting. Relay 1029 is operated from battery through its winding, brush arm 1022 and its associated terminal, conductor 1038, right winding of relay 501, lower right contact of cam 806, upper right contact of cam 805, conductor 814, left front contact of relay 601, conductor 804 to ground at the right back contact of relay 803. With the line finder selector resting on its first terminal, relays 1307 and 1317 are operated and sequence switch 900 is held in position 2, as previously described for a routine test. Key 875 is then operated, advancing sequence switch 800 to position 5. Dial 873 is next operated causing the line finder selector to step to the desired terminal. As the line finder selector is stepping to the desired terminal relay 872 opens and closes at its right back contact, a circuit for stepping class selector magnet 1310 so that its selector switch is stopped on the terminal corresponding to that on which the line finder comes to rest. After the stepping of the class and line finder switches key 875 is again operated, and sequence switch 800 is advanced to position 6 in the same manner as previously described. From this point on the test proceeds in the same manner as that described for a routine test. If, after the completion of the test of this particular district circuit, it is desired to resume routine test on subsequent circuits, key 6 is restored to normal after sequence switch 800 leaves position 5. After key 6 has been restored to normal, sequence switch 800 remains in position 18 after the completion of the test. If a spare terminal is selected by this process, sequence switch 800 may be returned to position 18 by the operation of control advance key 2.

Repeat 1st revolution tests.

If it is desired to repeat a test upon a certain district selector, one of keys 3, 7 or 8 is operated depending upon which revolution of sequence switch 800 it is desired to repeat the test, key 3 being operated to re-

peat the first test, key 7 for the second test and key 8 for the third test. Suppose it is desired to repeat the first test. Key 3 is operated, and the circuit for advancing sequence switch 900 out of position 2 and into position 3 is opened at the contacts of this key. This circuit, it will be remembered, was traced from battery through the winding of the power magnet of sequence switch 900, upper contact of cam 928, conductor 9, normal contacts of key 3, conductor 26, outer right front contact of relay 1204, conductor 847, lower left contact of cam 822, to ground on conductor 818. The circuit through line finder selector magnet 1030 is also opened by the operation of this key, preventing the line finder brush assembly from stepping to the next terminal. This circuit was traced from grounded battery through the winding and back contact of magnet 1030, outer front contact of relay 1029, conductor 1008, right contacts of cam 808, conductor 809, back contact of relay 609, inner right back contact of relay 610, conductor 611, normal contacts of keys 6, 8, 7, 8 and 2, conductor 12, upper right back contact of relay 1201, conductor 1206, intermediate back contacts of relays 1304 and 1305, next to the inner back contact of relay 1306, next to the inner front contact of relay 1307, conductor 1332, left contact of cam 906, conductor 907, inner right back contact of relay 1207, conductor 1218, upper contact of cam 819 to ground at conductor 818. With sequence switch 800 in position 16, a circuit may be traced for advancing this sequence switch out of position 16, from battery, through the windings of sequence switch 800, upper left contact of cam 838, conductor 841, operated contact of key 3, conductor 849, to ground at the lower contact of cam 848. When sequence switch 800 reaches position 18, it is advanced out of this position over a circuit which may be traced from battery, through the winding of sequence switch 800, lower left contact of cam 823, conductor 862 to ground at the operated contact of key 3. The circuit for operating relay 1222 which was traced from the normal contact of key 3 is opened by the operation of this key, preventing the energization of this relay and the subsequent operation of register 1224 upon the repetition of the test. With these exceptions as noted, the test proceeds identically as described for routine test during the first revolution of sequence switch 800.

Repeat 2d revolution tests.

In order to repeat the test made during the second revolution of sequence switch 800, key 7 is operated. It will be remembered that during the second revolution of the sequence switch a circuit for energizing stepping magnet 1030 was traced through the normal contacts of key 7 so that upon the

operation of this key the line finder connector is prevented from stepping to its next terminal. The operation of key 7 closes a circuit for advancing sequence switch 800 out of position 18 which may be traced from 70 grounded battery through the winding of the power magnet of the sequence switch, lower left contact of cam 823, conductor 862 to ground at the operated contact of key 7. Sequence switch 900 is prevented from advancing out of position 3 over the circuit which was traced through the upper front contact of relay 1213. This is accomplished because the energizing circuit of relay 1213 is opened at the normal contact of key 8. 80 When sequence switch 800 is advanced from position 18 it is advanced to position 2 over the circuit which was traced from the lower right contact of cam 801, conductor 802, left back contact of relay 1201, outer right back 85 contact of relay 1202, conductor 1203, operated contact of key 1 to ground at the normal contact of key 2. From this point the repeated test of the second revolution of sequence switch 800 is performed in a manner 90 similar to the routine test on its second revolution. The test circuit continues to repeat the test until the key is released.

Repeat 3d revolution tests.

95

The third revolution test is repeated upon the operation of key 8. The circuit for advancing sequence switch 800 out of position 18 is closed to ground at the operated contact of this key. The circuit for operating the stepping magnet 1030 associated with the line finder connector is opened at the normal contact of this key, preventing the line finder connector from stepping to the next terminal. This key also opens at its contact 100 the energizing circuit of relay 1213, preventing sequence switch 900 from advancing out of position 3. The third revolution test is then repeated in the usual manner. When key 8 is restored to normal the circuit continues to make its routine test. 105

Stop automatic test.

The automatic test may be halted at any time by the restoration of start key 1 to its 115 normal position. A circuit may be traced from battery through the winding of the sequence switch power magnet, lower right contact of cam 828, conductor 871 to ground at the normal contact of key 1 advancing the sequence switch from any position in which it may be at that time to its normal position 1. A circuit for advancing sequence switch 800 out of position 1 is opened at the contact 120 of this key and sequence switch 800 will remain in its normal position. If it is desired 125 also to restore the test circuit completely to normal after releasing key 1, key 5 is then operated and the circuit restored in the manner similar to that previously described for 130

the operation of key 5. When it is desired to stop the automatic test of a particular circuit keys 1 and 6 are released and key 5 is operated.

5 *Pass busy key.*

When a busy district circuit is encountered by the line finder connector in the case of a 10 routine test it remains on the terminals until the district is released and the test circuit remains inactive. It may sometimes be necessary to pass over districts which are 15 busy and the test circuit has been so arranged by the insertion of key 4. When the 20 line finder connector is stepped to the terminals connected to a busy district relays 14, 10, 1216, and 619 are operated and when key 4 is operated to effect a pass by, these 25 relays lock until sequence switch 800 leaves position 17. The locking circuit for relay 14 may be traced from battery, lower contact of cam 820, conductor 821, left winding of 30 relay 14, operated contact of key 4 to ground at the right front contact of relay 14. Relays 1216 and 619 lock over conductor 1220 to ground at the right contact of relay 14. Upon the energization of relay 1216 busy 35 register 27 operates from grounded battery, winding of the register magnet, operated contact of key 4, conductor 28, inner right front contact of relay 1216, right back contact of relay 1209, conductor 1210 to ground at the upper left contact of cam 901. Sequence 40 switch 800 is advanced to position 18 in a circuit from grounded battery, winding of the power magnet of sequence switch 800, lower right contact of cam 823, conductor 824, operated contact of key 4, conductor 29, innermost left front contact of relay 1216, 45 outer left front contact of relay 1204, conductor 1239 to ground at the lower right contact of cam 843. With sequence switch 800 in position 18, the line finder connector 50 is advanced to the next terminal as described for an ordinary test. Relay 1201 was released upon the operation of relay 1216 since its holding circuit was traced through the outer left back contact of relay 1216. Sequence 55 switch 900 remains in position 2. Sequence switch 800 is then advanced from position 18 into position 1 in a circuit which may be traced through the front contact of relay 612. When this relay energizes as a 60 result of the stepping of line finder connector 1030, the circuit is in condition to test the next district.

If, during the interval that the district 65 is released by the test circuit when sequence switch 800 is passing from its first to its second or from its second to its third revolution, it is seized and made busy by a calling subscriber's line, relay 14 is energized in position 6 of sequence switch 800 and as a result, relays 1216 and 619 operate. The

circuit then functions in a manner similar to that just described.

Provision for two test circuits.

In some telephone exchange offices, it is 70 sometimes necessary to utilize two test circuits for testing district selectors. In that case an extra set of terminals is set apart on the district frame for the second test circuit, above that of the first. This condition 75 is shown in Fig. 5 where the second test circuit has been represented within the rectangle marked 500. Both of the test circuits may now use the test line code and the same group of trunks, relays 552 and 553 being 80 provided to prevent simultaneous hunting by two district selectors for the district test line. If the test circuit associated with terminals 455, 456 and 457 arrive into the position 85 for sending impulses into the sender before the test circuit associated with terminals 420, 421 and 422 relay 624 will be operated. A circuit may then be traced from grounded battery through the windings of relay 552, inner left back contact of relay 553, conductor 824 to ground at the right front contact of relay 624. Relay 552 is energized in this circuit, opening at its right back contact the energizing circuit of relay 553. By preventing the operation of relay 90 553, terminal 457 is not made busy by the ground at the right front contact of this relay. Conductors 554, 555 and 556, which are opened at the outer left normal contacts of relay 553, are held open, preventing the test circuit 500 from functioning. If, now, test circuit 500 is in position for sending impulses to the sender before the test circuit shown in this disclosure, relay 553 operates 95 in a circuit from battery through the winding of relay 553, right back contact of relay 552, conductor 555 to ground at the front contact of the relay corresponding to relay 624 in test circuit 500. Relay 552 is then 100 prevented from operating and terminal 457 is made busy from ground at the right front contact of relay 553 so that the district selector circuit will hunt over the first three sets of terminals and come to rest on the fourth set. When the district selector reaches 105 its line terminals, relay 504 energizes, releasing relay 552 which was locked through the back contact of relay 504 to ground on conductor 1330. Relay 553 is then in a position to operate and lock until 110 the district selector reaches its test line.

What is claimed is:

1. In a telephone exchange system in which a link circuit is employed for establishing connections between calling and called lines, said link consisting of a calling line finder switch, a sender finder switch and an outgoing trunk hunting switch, a testing device consisting of means to perform a progressive series of tests to de- 125

- 135

- termine the accuracy of operation of said link circuit.
2. In a telephone exchange system in which a link circuit is employed for establishing connections between calling and called lines, said link circuit consisting of a calling line finder switch, a sender finder switch and an outgoing trunk hunting switch, a testing device to cause said link circuit to operate in simulation of its connecting functions and means to indicate unstandard conditions in said link circuit.
3. In a telephone exchange system in which a link circuit is employed for establishing connections between calling and called lines, said link circuit consisting of a calling line finder switch, a sender finder switch and an outgoing trunk hunting switch, said line finder switch consisting of a movable set of brushes, a testing device, means in said testing device for initiating the movement of said set of brushes, and means to check whether said brushes have moved in response thereto.
- 25 4. In a telephone exchange system in which a link circuit is employed for establishing connections between calling and called lines, said link circuit consisting of a calling line finder switch, a sender finder switch and an outgoing trunk hunting switch, said line finder consisting of a movable set of brushes a testing device for performing a progressive series of tests upon said link circuit, means for initiating the movement of said set of brushes, and means to arrest the progression of said testing device upon failure of said set of brushes to move.
5. In a telephone exchange system in which a link circuit is employed for establishing connections between calling and called lines, said link circuit consisting of a calling line finder switch, a sender finder switch and an outgoing trunk hunting switch, said line finder switch consisting of a movable set of brushes whose operation is under the control of a relay, a testing device for performing a progressive series of tests upon said link circuit, a group of timing relays and an interrupter in said testing device, said relays and interrupter operative to halt the progress of said testing device upon the failure of said first relay to cause the operation of said set of brushes.
- 40 6. In a telephone exchange system in which a link circuit is employed for establishing connections between calling and called lines, said link circuit consisting of a calling line finder switch, a sender finder switch and a trunk hunting switch, said line finder switch consisting of a bank of terminals and a vertically movable set of brushes cooperating therewith, a testing device, conductors from said testing device extending to terminals on said bank, means in said testing device to cause said set of brushes to come to rest upon said terminals and means to determine whether or not said set of brushes overstep said terminals.
- 45 7. In a telephone exchange system in which a link circuit is employed for establishing connections between calling and called lines, said link circuit consisting of a calling line finder switch, a sender finder switch and a trunk hunting switch, said line finder switch consisting of a bank of terminals and a vertically movable set of brushes cooperating therewith, a testing device for performing a progressive series of tests upon said link circuit, and a relay operative to halt the progress of said testing device upon the failure of said set of brushes to rest upon said terminals.
8. In a testing system for testing automatic selector switches, a testing device and means in said testing device for selecting a particular switch for test, said means comprising selective switches, a calling dial, and a relay for controlling said selective switches responsive to the operation of said calling dial.
9. In a testing system for testing automatic selector switches, a testing device, means in said testing device for selecting a particular switch for test, said means comprising selective switches, a calling dial, and a relay for controlling said selective switches responsive to the operation of said calling dial, and further means in said testing device for indicating the accuracy of operation of the particular switch selected for test.
10. In a testing system for testing automatic selector switches, a testing device, and means in said testing device for selecting a particular switch for test, said means comprising a plurality of pyramidially grouped selective switches, a calling dial, and a relay under the control of said dial for governing the setting of said selective switches.
- 105 11. In a testing device arranged to test switching links, said links consisting of a line finder switch, a sender finder switch and an outgoing trunk finder switch, a sequence switch, means for advancing said sequence switch through a plurality of revolutions for applying a plurality of series of tests to said link, a different series of tests being made during each revolution of said sequence switch, and means to repeat any one of said plurality of revolutions.
- 110 12. In a telephone exchange system in which a link circuit consisting of a line finder switch, a sender finder switch and an outgoing trunk finder switch is employed for completing connections from a calling line, said link circuit having a message registration controlling circuit including a plurality of multiple resistances, a testing device, including a relay and means for associating said relay with said controlling
- 115 130

circuit, said relay operative when any or all of said resistance elements are short circuited, and means under the control of said testing device for indicating that said relay 5 has operated.

13. In a telephone exchange system in which a link circuit consisting of a line finder switch, a sender finder switch and an outgoing trunk finder switch is employed 10 for completing connections from a calling line, said link circuit having a message registration controlling circuit including a plurality of multiple resistances, a testing device for performing a series of routine tests 15 upon said link circuit including a relay and means for associating said relay with said controlling circuit, said relay operative when any or all of said resistance elements are short circuited, and means under the 20 control of said relay for halting the performance of said series of routine tests.

14. In a telephone exchange system in which a link circuit consisting of a line finder switch, a sender finder switch and 25 an outgoing trunk finder switch is employed for completing connections from a calling line, said link circuit having a message registration controlling circuit including a plurality of multiple resistances, 50

a testing device including a relay and means 30 for associating said relay with said controlling circuit, said relay normally operative when all of said resistance elements are intact and inoperative when any or all of said elements are open and means under the 35 control of said testing device for indicating whether or not said relay has operated.

15. In a telephone exchange system in which a link circuit consisting of a line finder switch, a sender finder switch and an outgoing trunk finder switch is employed 40 for completing connections from a calling line, said link circuit having a message registration controlling circuit including a plurality of multiple resistances, a testing device 45 for performing a series of routine tests upon said link circuit including a relay and means for associating said relay with said controlling circuit, said relay normally operative when all of said resistance elements 50

are intact and inoperative when any or all of said elements are open, and means under the control of said relay for halting the performance of said series of tests upon the failure of operation of said relay. 55

In witness whereof, I hereunto subscribe my name this 17 day of May A. D., 1924.

EDWIN F. TRAPP.
